TRAFFIC CONTROL SYSTEM FOR SELECTION AMONG MULTIPLE OFFSETS AND MULTIPLE CYCLE LENGTHS IN RESPONSE TO THE LEVELS OF TWO MEASURED TRAFFIC CHARACTERISTICS

Charles L. Du Vivier, Darien, Conn., assignor to Laboratory for Electronics, Inc., Boston, Mass., a corporation of Delaware

Filed Sept. 18, 1961, Ser. No. 138,827

7 Claims. (Cl. 340—36)

This invention relates to an improved traffic actuated control system of the master-local controller type and particularly to greatly improved actuated control apparatus including a master controller for use in a traffic control system, which is responsive to traffic actuation, and local controllers, which may be traffic actuated or non-traffic actuated but yet responsive, when desired, to control of a master controller, in varying degrees of control, upon predetermined traffic conditions of the roadway over which the traffic is traveling.

In order to provide an efficient operating master-local traffic control system it is desirable to provide at least a common control function to all local controllers in the control system from the master controller to which the local controllers may respond in common. One such control is referred to as a coordination or synchronization control which, in effect, provides a supervisory function over the local controllers and keeps the local controllers "in-step." This does not necessarily mean simultaneous operation of the local controllers although such coordination control may be employed to provide simultaneous operation.

A common coordination control may be used to maintain the signal cycles of adjacent local controllers at certain relationships with each other, which is accomplished by establishing desired individual displacements of the local controller cycles from the master cycle as a reference, this displacement of the local cycle from the reference being commonly referred to as the "offset." During simultaneous operation of the local controllers, that is with the green signals changing at all controllers simultaneously, it may be considered that no "offset" of the signal cycle is in effect or that all of the controllers have a "zero offset."

It has been found, in the field of traffic control, that three basic offset conditions may be efficiently employed in a traffic control system. These three basic offset conditions may be based on the relative difference or a predetermined differential between the value or count of traffic characteristic of traffic volume for example. For convenience of description these three basic offset conditions will be referred to as "average offset" or "average," which may prevail when both traffic flows are substantially equal, or unequal but are within a predetermined difference in value, "inbound offset" or "inbound" which may prevail when the inbound traffic flow exceeds the outbound traffic flow by a predetermined value, for example, and "outbound offset" or "outbound" may prevail when the outbound traffic flow exceeds the inbound traffic flow by a predetermined value.

It should be noted that the mentioned offsets are basic offsets and each may be further broken down into degrees of traffic offset conditions depending upon the offset conditions and the total amount of the traffic on the entire roadway, such as, for example, light traffic, average offset, when both traffic flows are substantially equal and the total traffic is light, medium traffic, average offset, when both traffic flows are substantially equal and the total traffic on the roadway is medium or moderate, and heavy traffic, average offset, when traffic flows are

2

substantially equal and the total traffic is heavy, and so forth.

The relative traffic offset conditions may also be broken down on a finer basis, if it be desired, such as on a percentage basis using a predetermined number of vehicles in the traffic flow as 100 percent and determining the percentage proportionally, with the number of vehicles.

A percentage of traffic value may be based on a count over a substantially short sampling time period as for example six to ten minutes and may indicate zero percent when no vehicles are counted on the roadway during the sampling period, for example, and may indicate 100% when a predetermined number of vehicles is counted during the sampling period. The predetermined number of vehicles representing 100% may be the number of vehicles that the roadway was designed to carry as full capacity. Obviously, the one hundred percent value of traffic on a roadway may mean that the traffic count or value is such that the number of vehicles present on the roadway is all that the roadway is capable of handling and still maintain reasonable traffic flow.

A percentage of traffic above one hundred percent, may mean that the number of vehicles present on the roadway is in excess of the number of vehicles the roadway was designed to carry.

Relative traffic conditions on a roadway may be made to affect a traffic control system in different ways, as for example, with an offset condition of average, inbound or outbound determined by the differential between two measured traffic flows, the percentage of offset between adjacent controllers may be made variable relative to the volume of the highest traffic flow or aggregate of the traffic flows on the roadway.

Various percentage of offset between adjacent controllers may be locally adjusted but may be remotely selected according to either the percentage of the higher of the two traffic flows or according to the percentage of the total traffic flow. This condition is more easily understood relative to inbound and outbound offset conditions than average offset conditions since average offset may very often provide balanced or simultaneous operation of the local controllers. While both inbound and outbound offset may shift the signal cycle of adjacent controllers so that the start of the signal cycle of one local controller is offset with respect to the start of the signal cycle of another local controller the degree of offset may be varied according to the amount of traffic.

Traffic value or count on a roadway may also affect a traffic control system by varying the length of the signal cycle, as for example, light traffic conditions may provide a short signal cycle and, as the traffic count increases, the length of the signal cycle may vary accordingly, as desired, either proportionally or non-proportionally, with the count or measurement. The length of the traffic signal cycle may also vary or be varied according to the traffic volume attaining a certain predetermined value or level, with as many levels as desired for varying the signal cycle length, as desired.

Further, a combination of prevailing traffic conditions on a roadway, such as relative traffic conditions between traffic flows and traffic value or count may be employed to provide various changes in a traffic control system. As for example, the combination of the two factors of relative conditions between traffic flows and traffic value or count of the higher of the two traffic flows above may be used to vary uniformly the length of the signal cycle. Along these lines, the length of the signal cycle may be varied according to the offset condition prevailing with the offset condition controlled by the combination of relationship between the two traffic flows plus the value of the higher of the two traffic flows and the degree of offset controlled solely by the total traffic value or count.

Further the offset condition may be controlled solely by relationship between two traffic flows and the signal cycle length may vary solely according to the value or count of the higher of the two traffic flows with the degree or amount of offset varied according to the length of the signal cycle selected. Thus, in the latter mode of operation, a predetermined relationship between the degree or percentage of offset and the length of the signal cycle may be maintained although the offset condition and the signal cycle length may be determined independently of each other.

This latter effect of traffic conditions such as the value of traffic flow measurements and relationship between traffic flows in a traffic control system may provide for an extremely versatile and flexible control system when the traffic flow measurements and the relationship between traffic flows are representative of the substantially current traffic flow on the roadway. Effect of substantially current traffic conditions on traffic control systems has been substantially limited to relatively highly complex, expensive and massive electronic and electro-magnetic equipment.

Such complex and massive electronic and electro-magnetic equipment has certain disadvantages since the cost of procurement of such equipment is substantially high and such expenditure may be justified by extensive and far reaching use of the same, such as in relatively large traffic control systems which may employ many local controllers supervised by one master controller. Further, installation and maintenance of this complex master controller and system occasionally presents other problems since highly skilled technicians are usually required to install, maintain and repair the master controller and the local controllers of the traffic control system. The massiveness also presents a problem of storage.

The present invention provides a greatly improved master controller in part electronic and in part electro-magnetic, responsive to substantially current demands of traffic, such demands determined through actuation of a sampling of at least two traffic flows one on one or more roadways. The electronic part of the master controller may be provided as a substantially simplified counting or measuring device such as a simplified traffic volume counting circuit or a simplified traffic density determining circuit or a simplified traffic speed averaging circuit or other simplified circuit to measure or determine any other characteristic of a traffic flow, each of which may be operated and the value or count determined by actuation of a sampling of the vehicles in the traffic flow.

The preferred embodiment of the improved master controller includes two identical traffic flow characteristic determining and measuring units, as for example traffic volume determining and measuring units, each of which may determine the volume of traffic, for example, on one or more traffic lanes of one or more substantially similar traffic flows and maintain a substantially running count, measurement or value of traffic volume, for example, so that the two separate counts, measurements or values of a similar traffic characteristic are of substantially current traffic. Associated with each determining and measuring unit is a comparing unit, each of which is interlocked with the measuring unit with which it is not associated.

As will be more fully described with reference to the accompanying drawing, the traffic characteristic determining and measuring unit of each traffic characteristic determining, measuring and comparing component senses and measures, through actuation of a sampling of the vehicles in the traffic flow, the traffic characteristic to be determined and measured. Such traffic characteristic may be the volume of traffic the measurement of which may be calibrated in vehicles per unit time, or traffic density, calibrated in the number of vehicles per unit length of roadway, or average speed of the traffic flow, calibrated in miles per hour.

The output of each traffic (D.C.) voltage which may vary from 0 to +100 volts and may represent from 0 to 100% of a predetermined value of the traffic characteristic determined. Each D.C. voltage from each measuring unit is applied to several associated individually adjusted level response or "pick-off" circuits which make up the preferred form of comparing unit and each D.C. voltage is also applied to one of the response circuits of the other comparing unit to become a reference from which a predetermined differential between the two D.C. voltages may be determined.

TRAFFIC LEVEL RESPONSE CIRCUITS—GENERAL

15 Each traffic characteristic comparing unit includes an identical number of individual level response circuits, each of which may be individually adjusted to respond to a predetermined level or value of the D.C. output and further, to stop responding at another separately adjustable level or value of the same D.C. voltage.

20 As described below the preferred embodiment of master controller is provided with at least two vehicle detection or vehicle actuated input circuits, with at least one input circuit for each traffic characteristic, for example volume, determining unit, two separate and identical traffic volume

25 determining and measuring units and a comparison unit including at least four dual-adjustable level response circuits, associated with each volume determining unit. Each level response circuit is connected to the output of

30 its associated measuring unit, with one of the level circuits of each comparison unit connected to the output of the measuring unit of the other determining, measuring and comparing component. Thus the D.C. voltage output, representing one volume measurement of one measuring unit becomes a reference level for the level

35 response circuit of the other determining, measuring and comparing component so that response to at least a predetermined differential between the two electrical values may be obtained by operation or response of one or the other of the correspondingly connected level response circuits or no response obtained from either of the level response circuits, according to the differential between the two electrical values.

The first, second and third of the series of response 45 circuits may be adjusted so that response may be sequentially provided by the first, then the second and then the third response circuit, etc., as the level of the associated D.C. voltage increases, with the individual levels of response individually adjustable so that although the response may be made sequentially, the various levels at which the response circuits may respond need not be uniformly separated. Further, each of the response circuits are also adjustable so that cessation of response may be made at a different level than initiation of response of the same circuit.

50 55 Thus the improved master controller may provide separate internal response to various levels of electrical energy, the value of which represents a level or volume of traffic and also may respond to the relation between two electrical energies which response may represent at least a predetermined differential between the two electrical energies. Response to various levels of each electrical energy may be individual to each determining, measuring and comparing component with or without uniform or similar differentials between the various levels of response.

60 65 Response to a predetermined relationship or differential between the two electrical energies may be made without regard to the relative amplitude of the energies so long as the differential between the electrical values is at or exceeds a minimum preset value or differential.

RESPONSE TRANSLATING COMPONENT—GENERAL

70 75 The response reflected by the individual response circuits, which may represent current traffic conditions and

current relation between the traffic flows, is applied to a simplified electro-magnetic response translating component. Since the traffic value of both traffic flows are independently represented and the relationship between the two traffic flows is also independently represented, the preferred embodiment provides that these representations, be translated and converted into an output from the master controller so that the output may represent current traffic conditions on the roadway.

The response translating component which is associated with the two traffic characteristic determining, measuring and comparing components is arranged so that a mode of operation may be selected from a variety of modes of operation depending upon the degree of flexibility and versatility of the master controller desired.

Primarily the response translating component provides an output which may control one or more local controllers in a traffic control system by "calling" or "demanding" one or another general traffic plan, selected according to the general traffic conditions on the roadway. The output is the output of the master controller of which each of the above mentioned components is a part. This output is extended to all the local controllers in the traffic control system and uniformly received. The output may be made up of a group of energized and/or deenergized leads, the combination of which may vary according to response by the comparing units and the mode of operation of the response translating component. Selection of one of several timing devices within the response translating component may be made according to response of the comparing units. The output of the master controller may be maintained for a period timed by the selectable timing device during which no change in output may occur but after which a change in output may occur according to translation of the response of the traffic characteristic determining, measuring and comparing components, at which time not only may the output be changed, but a new selection of a timing device may be made.

In the preferred embodiment of the master controller, a periodic coordination output pulse may be provided to all local controllers in the traffic control system at all times when the master controller is in operation. This coordination output pulse may maintain coordination among the local controllers and between each local controller and the master controller, however, it may be desired to release one or more of the local controllers in the control system from coordinated operation. This may be accomplished by local adjustment of the individual controller. This provides for permitting "isolated" operation or "setting free" of any one local controller in the control system without interfering with the coordinated operation of the other local controllers.

The output of the master controller also includes output leads for providing control of the offset of the signal cycle of each of the responsive local controllers. With respect to local controller response to the offset control output of the master controller, each local controller may respond independent of each other local controller and thus may be made to respond in a different degree to the same call or demand, depending upon local adjustment of the individual local controller. The section or part of the response translating component which provides the output for offset control includes the optional feature of providing a combination of available outputs which may demand or call for, what may be referred to as, "free" operation of the local controllers under certain traffic conditions. "Free" operation may be the condition of operation where no offset condition prevails, which may be desired during very light traffic conditions. "Free" operation of the local controllers may be eliminated, so that one or the other offset condition may be maintained at all times, as desired. Further, provision is made so that certain desired local controllers in the control system may go "free" while other local controllers may be

in an offset condition in response to the same master controller output. It should be noted that the term "free" operation differs from "isolated" operation in that during "free" operation the local controllers may still remain coordinated but in an "isolated" operated condition the local controller may be released from all master control.

The selection by the response translating component, of an offset condition, for output to the local controllers, may depend upon the relationship between the two traffic flows, as expressed by the response of corresponding level response circuit of either one of the traffic characteristic determining, measuring and comparing component. The relationship between the two traffic flows is determined by using the level or value of electrical energy of one traffic characteristic determining, measuring and comparing component as a reference for the other traffic characteristic determining, measuring and comparing component, thus each electrical value may become a reference for the other electrical value and as such, response may be made by one or the other corresponding level response circuit to a preselected differential between the two electrical energies. Such response may be conditioned upon at least one electrical energy or voltage value or traffic level increasing to or above a minimum predetermined level, or response may be made directly upon one electrical value increasing above the other, to or above a predetermined differential between the two electrical values without regard to the actual level of electrical value or traffic level.

30 OFFSET CONTROL AND CYCLE LENGTH CONTROL PARTS OF RESPONSE TRANSLATING COMPONENT

The improved master controller herein presented further includes an additional feature heretofore unutilized in simplified master controllers of this general type. The current offset conditions are internally expressed in one part of the response translating component by application of power to one or more of several internal terminals, which power is applied through a network of circuitry controlled by the same response components by which offset conditions are determined. Power applied to any one or more terminals may be applied to the second section or part of the response translating component through jumper connections adjusted as desired, so that certain desired signal cycle length control circuits, which provide one part of the total output of the master controller, may be associated with any one or more offset conditions so that the cycle length output control may be made to respond, as desired to the offset control part of the response translating component or may be made independent of the offset control part so that offset control and cycle length are determined independent of each other or combined in varying degrees, as desired, so that varying degrees of flexibility of the master controller itself, are available through adjustment of the jumper connections between the two sections of the response translating component as desired.

Referring particularly to the second section of the response translating component, this second section may be subdivided into three sub-sections, the first sub-section may be the timing section which may include three timing motors or "synchrolizers," each of which may be selectable according to preselected traffic levels, and/or may be otherwise selected according to the mode of operation of the master controller, in cooperation with the first section as determined by the connections made by the jumper leads.

70 MODES OF OPERATION OF CYCLE LENGTH SECTION OF RESPONSE TRANSLATING COMPONENT

According to the preferred embodiment of this greatly improved master controller, one mode of operation may provide for selection of a certain one of three timing de-

vices or "synchrolizers" directly according to the level or value of traffic as determined by at least one of the traffic volume determining, measuring and comparing components. One synchrolizer out of three is selected, when both levels or values of traffic volume are below individually preselected minimum values respectively; another synchrolizer is selected when one or both levels are at or above an individually preselected minimum value but neither value is at or above individually preselected maximum values and a third synchrolizer is selected when one or both levels are at or above individually preselected maximum values of traffic volume.

Another mode of operation may provide selection of one or the other of the synchrolizers directly according to the relationship between the two traffic flows without regard to the levels of traffic volume. A further mode of operation, as selected by the jumper connections between the two parts or sections of the response translating component, may provide for selection of one or the other of the synchrolizers according to a selected combination of offset conditions and selected levels of traffic volume. An additional mode of operation provides for manual selection of one of the synchrolizers over the others, if desired.

Each synchrolizer may be adjusted to complete a cycle of operation in a different length of time, as desired. Each synchrolizer controls a set of cams or cam contacts each set being substantially similar, with one pair of cams in each set of contacts of each synchrolizer being part of a series circuit employed to energize a locking relay, when all the cam contacts are closed. At a predetermined part of each cycle of operation, as for example just prior to termination of each cycle of operation, the lock relay is operated by all the series connected contacts being closed. Operation of this relay permits translation to take place in the response translating component. During a certain part of the cycle of operation, as indicated on the cam sequence chart among the several drawings, selection of one of the three synchrolizers is made, although the synchrolizer selected may be the same synchrolizer which controlled the last cycle, and the selected synchrolizer is initiated into operation while the other synchrolizers remain at rest. In addition, a coordination control relay is released by the opening of another pair of cam contacts just prior to termination of the cycle of operation of the operated synchrolizer. The coordination control relay controls one of the output leads which may be deenergized for a short time and then energized thereafter. This coordination output lead may initiate local controllers into operation and in effect start all the local controllers at the same time. The remainder of the output leads of the response translating component operate in conjunction with selection of a synchrolizer provide for selection of a cycle length control means, from several cycle length control means in the local controller which controls the signal cycle length of the local control. The remaining cams or cam contacts provide a self-driving circuit for self-operation of the selected synchrolizer after the selected synchrolizer is initiated into operation and then is isolated from the initiating circuit.

During the period in which translation of response to traffic conditions is made the self-driving circuit cams are open and the selected synchrolizer is initiated into operation through selective circuitry in cooperation with contacts of the lock-relay, depending upon the mode of operation obtained by selection of the jumper connections.

Cooperation between the synchrolizer controlled lock relay and the self driving cam contact is provided so that selection of one of the three synchrolizers and an associated output may be made only at termination of the cycle of operation of the last selected synchrolizer. One synchrolizer is selected and initiated into operation after which the selected synchrolizer is electrically isolated from the selecting and initiating circuitry so that once selection of a synchrolizer is made, the master controller may not make another selection of synchrolizer and associated out-

put for at least a minimum time period as timed by the selected synchrolizer.

The third sub-section of the second section includes the jumper connection leads and circuitry for translating the response of the second and third level response circuits of the traffic characteristic determining, measuring and comparing components.

Upon examination of the circuitry of this section of the response translating component, it may be readily seen that the type of final output of this improved master controller may be varied, as desired, so as to include the total possible output combinations of the five output leads or the output leads may be reduced in number so as to include output combinations of less than five leads. Further when the total possible output leads are employed one or more of a variety of modes of operation may be selected as described above.

From another aspect the present invention provides an improved master-local traffic control system employing a master controller including the features described above and further including local controllers which may be of the non-traffic actuated or may be of the semi-traffic actuated type local controller or may be of the full traffic actuated type local controller or any combination of two or more different types of local controllers included in the same traffic control system. However, although each of the local controllers may be of any one of the various types of local controllers mentioned, local controllers may be either two phase controllers, that is according control of traffic at an intersection of two roadways or two interfering traffic flows or three phase controllers, that is according control of traffic at three intersecting roadways or two intersecting roadways plus a pedestrian traffic movement, or three interfering traffic flows, each local controller in the traffic control system need be, in some degree responsive to actuation by the master controller.

COORDINATION UNIT AND SIGNAL SWITCHING CONTROL UNIT PARTS OF LOCAL CONTROLLER

In the preferred embodiment of the improved master-local traffic control system the local traffic controllers may be divided into two parts, a first part which may be referred to as a coordination unit and a second part which may be referred to, for convenience, as a signal switching device or control unit. The signal switching device may itself be a fully integrated local controller and may be capable of independent or "isolated" operation so that control of right-of-way at the intersection over which it exerts control may be maintained without requiring control from the master controller or the coordination unit.

Each coordination unit of each local controller in a traffic control system is connected to the output leads extending from the master controller.

When operating in a fully coordinated master-local traffic control system, the coordination unit may respond to demand or call from the master controller to select an offset and signal cycle length from several locally adjusted offsets and from several signal cycle lengths. The master controller sends out, what may be generally referred to as a "coded" output to each local controller in the traffic control system. Each different output combination or "coded" output from the master controller may represent a different demand to the local controllers and may be associated with, but not necessarily representing, a different condition of current traffic conditions. Upon initially receiving the particular output or demand from the master controller, each local controller interprets the coded output or demand and provides a traffic plan individual to the particular local controller, such traffic plan being preselected to be provided by the particular local controller upon receiving the particular coded output from the master controller. The particular traffic plan provided by any individual local controller may include a condition of offset of the signal cycle from a common part of the signal cycle of each local controller and/or a particular preselected

signal cycle length and/or a preselected distribution of cycle or split among the several phases, or a traffic plan excluding one or two of the enumerated features. The coordination unit receives the output of the master controller and interprets the particular output for that particular local controller.

The coordination unit, after interpreting the output of the improved master controller provides an output of its own and applies its output to the signal switching device which output may represent a certain preselected traffic signal plan of offset, signal cycle length and/or call for a certain preselected distribution of cycle or split of cycle from several splits of the cycle or any one or combination of two or combination of all three conditions, which may be individually preselected for providing more efficient flow of traffic at that intersection accordingly.

The preferred embodiment of the coordination unit may include three separate, independently operated, locally adjusted, remotely selectable signal cycle length timing means, one of which may be selected and operated to the exclusion of the other timing means according to the demand or call from the master controller and according to local adjustment of the coordination unit.

Each timing means may further be associated with several cams, each of which may be individually adjusted for providing a different offset condition. Thus each timing means may control a cam for providing average offset, a cam for providing inbound offset, and a cam for providing outbound offset, for example.

Although the preferred coordination unit provides for selection from among several separate signal cycle length timing means each of which may provide a different signal cycle length, obviously the number of selectable timing means may be reduced to selection between two timing means. This may be provided for by either making two of the timing means time the same signal cycle length or by reducing the available selection by reducing the number of timing means in the coordination unit. Various combinations of signal cycle length and various degrees of the same or different offsets are possible. As for example, three means for providing three different signal cycle lengths may be provided, each of the three cycle length means having associated therewith three different offset cam but, as among the cams of the same offset, each cam may be adjusted to a different degree of percentage of the offset. Thus for the same offset condition, selection of a timing means, may provide a different length signal cycle and each different length signal cycle may provide the same or a different degree or percentage of offset. However, the number of timing means may be reduced while the number of offset cams may remain the same and instead of selecting between different timing means, the same selecting circuitry, heretofore used for selecting between different timing means, may select between different degrees of percentage of offset for the same offset condition by selecting between differently adjusted offset cams of the same offset condition. Further the coordination unit may be adjusted so that selection between several timing means may be made, with each timing means providing a different length time cycle but with the offset cams of the same offset condition adjusted to the same degree or percentage of offset.

Each of the selected timing means, which may be, for example, in the form of a motor, may rotate its associated offset cams at different speeds of rotation, and its selected associated offset cams may close a cam contact and operate a relay at one or more certain desired parts or percentage points of the traffic signal cycle so as to provide an output pulse from the coordination unit to the signal switching device.

The coordination unit associated with each signal switching device may also include one or more networks of contacts and circuitry each of which cascades from a plurality of individually operated single pole switches connected to a common power supply and through a net-

work of relay contacts to provide an output from the coordination unit to the signal switching device when certain preselected output combinations are provided from the master controller. The single pole switches may be adjustable positioned to an open or closed position so as to supply output power to the signal switching device when the switch is closed and the selected output combination from the master controller is being received. As will be readily seen in the drawing, one or more switches may be positioned so that one or more output combinations from the master controller may provide the same output between the coordination unit and the signal sequence control unit.

The preferred embodiment of the coordination unit includes two such networks of manually operated, switch controlled, contacts and circuitry, although additional networks or one network may be provided if desired. Each network may be identical to the other and each may include as many as ten individual, manually controlled, locally adjustable switches. Of course, a "pile-up" of wafer switches may be used in lieu of the plurality of single pole switches in any one network if desired.

The signal switching device of the local controller may be in one of several different forms. Preferably, the signal sequence control unit may be in the form of a complete traffic signal controller which is capable of independent operation and which may respond to control from a master controller. One form of signal switching device may include means for providing two or more splits or distribution of the traffic signal cycle among the several signal phases, with any one split capable of being selected by the coordination unit according to adjustment of the single pole switches in the cascaded contact circuitry network and the output received from the master controller.

It is therefore an object of the present invention to provide an improved, actuated master controller of the electronic and electro-magnetic type, which is simplified, compact and relatively inexpensive.

Another object is to provide an improved master controller which may respond to two different traffic characteristics according to a predetermined relationship between the traffic characteristics and also according to the value of one or both traffic characteristics with the responding means individually and separately adjustable.

A further object is to provide an improved master controller which will provide response to various traffic conditions on a roadway and in particular to respond to a predetermined differential between the values of two different traffic flows and to provide other response to various preselected values of either or both traffic flows independent of the response to a predetermined differential.

An additional object is to provide an improved master controller in which selection may be made from one of three individually adjustable timing devices directly according to predetermined levels of traffic on a roadway or according to predetermined relationship between two traffic flows on a roadway or in accordance with preselected combined conditions of traffic expressed in response to a predetermined relationship between traffic flows and a response to predetermined levels of traffic on a roadway.

A still further object is to provide an improved master controller in which one of three offset selections is made according to relative traffic conditions on a roadway and in which one of three signal cycle length selections is made according to the level of one or more traffic flows, independent of relative traffic conditions.

Still another object is to provide an improved master controller whose components are included in one compact unit and in which such unit includes two identical traffic characteristic determining, measuring and comparing components, each component including a traffic characteristic determining and measuring unit, with each unit associated with multiple level response circuits or

determining circuits individually adjustable with each response circuit with each traffic characteristic measuring, determining and comparing component individually responsive to individually preselected levels of its associated traffic characteristic determining and measuring unit output with one response circuit of each determining, measuring and comparing component responsive to a predetermined differential between the two levels through application of the output of one of the two traffic characteristic determining and measuring units to the other traffic characteristic determining, measuring and comparing component so as to provide dual control of the differential response circuit and in effect make a difference level circuit out of one level response circuit for each determining, measuring and comparing component.

Still another object is to provide an improved master controller including two traffic characteristic determining, measuring and comparing components, each of which are identical, and are identically interconnected for determining, measuring and comparing each of two traffic characteristics and for selecting, according to the differential between such traffic characteristics one of several traffic offset conditions and for selecting, according to the level or value of either or both measured traffic characteristics, one signal cycle length from among several signal cycle lengths and for providing an output to local traffic controllers so that each local controller may select one traffic plan from a plurality of traffic plans preset in the local traffic controller, including different combinations of offset conditions and different signal cycle lengths according to traffic conditions.

A still further object is to provide an improved master controller whose several components include one component by which selection of one of three timing devices is selected for timing a selected output of the master controller during which time the selected output of the master controller may not change.

Another object is to provide a traffic responsive master-local traffic control system in which the master controller is a simplified, compact and relatively inexpensive electronic and electro-magnetic type master controller responsive to current traffic demands and which provides an output to the several local controllers of the traffic control system which may call for a coordinated plan of traffic which may include a signal cycle offset, the degree of offset, signal cycle length and distribution of the signal cycle in accordance with current traffic conditions and in which the local controllers of the traffic control system may be either of the traffic actuated or non-traffic actuated type.

Other objects will be apparent from the following description and claims when read with reference to the drawings in which:

FIG. 1 is a block diagram of a plan view of a traffic control system;

FIG. 2, including FIGS. 2 and 2a, is a diagrammatic view partly in block and partly in schematic form of one form of master controller;

FIG. 3 is a diagrammatic view of a simplified form of coordination unit which is part of a local traffic controller;

FIG. 4 is a diagrammatic view of a simplified form of signal sequence control unit which forms the other part of the local controller in the traffic control system;

FIG. 5 is a cam sequence chart illustrating one complete cycle of the cam driving mechanism.

FIG. 1—BLOCK DIAGRAM OF MASTER LOCAL TRAFFIC CONTROL SYSTEM

Referring to FIG. 1 in more detail, a plan diagram of a traffic control system is represented, in block form, with a master controller 20 and two local controllers 21 and 22, with the master controller providing output, via grouped leads 23, to the local controllers 21 and

22 and also extending to other controllers in the traffic control system.

The master controller 20 which is surrounded by a broken line box may represent the master controller 5 illustrated in circuit form in the combined FIGS. 2a and 2b with the circuitry in the left half of the broken line box 20 labeled FIG. 2a illustrated in FIG. 2a and the right side of the block diagram of box 20 labeled FIG. 2b illustrated in FIG. 2b. The local controllers 21 and 10 22 each including a box labeled FIG. 3 and FIG. 3 may represent the circuit diagram illustrated in FIG. 3 and FIG. 4 respectively. It will be noted that the local controller 22 is arranged for actuation by traffic on the cross streets through actuation of the detectors 15 22d and 22'd, while the local controller 21 is arranged for fixed time operation. Both local controllers 21 and 22 may be of the type described and illustrated in the combined FIGS. 3 and 4. It will be noted in the particular reference to FIG. 4 that the controller therein 20 illustrated may be operated as a fixed time unit or a traffic actuated unit as desired.

A roadway 24, serving two way vehicle traffic, as illustrated by the arrow marked inbound in the upper part of the roadway and the arrow marked outbound 25 in the lower part of the roadway is represented with two intersections 29 and 30. The vehicle traffic that pass through the intersections 29 and/or 30 is controlled by the signal lights represented by 31 and 32 respectively which signal lights are controlled by the local traffic 30 controller 21 and 22 respectively so that right-of-way is distributed between the main roadway 24 and the cross streets that make up the intersections of 29 and 30 respectively.

The rectangle 33 in the upper section of the roadway 35 24 and the rectangle 34 in the lower section of the roadway 24 each represent vehicle detectors in the respective lanes for detection of vehicles through actuation of the vehicles traveling in respective lanes and directions.

For the purpose of identification the traffic flow in the 40 upper lane shall hereinafter be referred to as inbound traffic while the traffic flow in the lower lane shall hereinafter be referred to as outbound traffic as indicated in the FIGURE 1.

As more fully described in the description below, the 45 inbound vehicles traveling in the upper lane of roadway 24, will actuate the detector 33 and according to the preferred embodiment, will cause closure of a pair of normally open contacts which will complete a circuit to energize a detector relay associated with one traffic 50 characteristic determining and measuring unit of the master controller which will consider each actuation of the inbound vehicles and determine the characteristic as for example volume, of the inbound traffic flow. The outbound vehicles, traveling in the lower lane of roadway 55 24, will actuate the detector 34 and will cause closure of a pair of normally open contacts to complete a circuit to energize a detector relay associated with the other, similar traffic characteristic determining and measuring unit of the master controller, which will consider each actuation of outbound vehicle traffic and determine traffic characteristics, for example the volume of the outbound traffic flow.

The detector devices 33 and 34 may be of the treadle 65 type which are located in a roadbed, essentially containing a pair of open contacts which are closed by passage of a wheel or wheels of a vehicle thereover or may be of any other type, well known in the art, such as microwave or radiant energy vehicle detector or any other type of vehicle detector sensitive to sound, light, heat, pressure 70 or magnetism, for example, which will cause closure of a set of normally open contacts upon actuation by a passing vehicle.

The grouped output leads 23 of the master controller 75 20, may, according to one embodiment, include five or

more leads, for example, which will each individually extend to each local traffic controller in the traffic control system. It may also be necessary to supply a common ground or return lead between the master controller and the individual local traffic controllers. This may increase the number of individual leads extending from the master controller to the local controllers but such return lead is omitted for convenience and simplification of the drawing.

In a traffic control system of the type represented, and of other similar types, it is desirable to coordinate operation of the individual controllers with the master controller and thus coordinate operation among the local controllers themselves, however, still maintaining certain of the operations of the individual local controller independent, so that, for example, start of the traffic signal cycle of one local controller may be offset from the adjacent or next adjacent, or other local controller in the system so as to stagger commencement of the green or "go" signal between local controllers to provide a more uniform flow of traffic along the signalized roadway.

MASTER CONTROLLER OF FIGS. 2a-2b

Referring now to FIGS. 2a and 2b, a diagram partly in schematic form and partly in block form is presented, of the preferred embodiment of a master controller with the combined figures, providing one form of the improved master controller.

The master controller illustrated in the combined FIGS. 2a and 2b may be represented in FIG. 1 by the block 20 with FIG. 2a representing the circuitry found in the left section of block 20 labeled FIG. 2a and the FIG. 2b representing the circuitry that may be found in the right section of block 20 labeled FIG. 2b. Referring particularly to FIG. 2a a series of blocks are illustrated in the lower half of the drawing and are numbered 50, 51', 52', 53' and 54'. The circuitry included in each of these blocks is identical to the circuitry illustrated in schematic circuit form in the broken line block directly above the respective solid line block and similarly numbered without the prime indication. Thus the circuitry in the broken line block 50 illustrates the circuitry that may be found in block 50' while the circuitry illustrated in the blocks 51, 52, 53 and 54 illustrates the circuitry that may be found in the blocks 51', 52', 53' and 54' respectively. Certain of the electrical components are illustrated in the lower blocks such as the relay 64' and the meter 121' etc. in block 50 and the relay 65' in block 51', the relay 66' in block 52', the relay 67' in block 53' and the relay 68' and triode 70' and interconnecting circuits 69 and 69' etc. in block 54' since the function of these relays although similar in response to the circuit to which they are a part as the corresponding relays and components illustrated above of corresponding numbers serve another and separate traffic flow.

Referring particularly to FIG. 2b, relays 65 and 65', 68 and 68', 66 and 66', 67 and 67', illustrated in broken line form, are merely displaced duplicates of the relays identically numbered in FIG. 2a.

FIGS. 2a and 2b have been presented in the manner shown in order to provide a more convenient description, however it should be understood that the improved master controller represented by the combined figures comprises a complete unit, the component parts of which serve to provide information from at least two sources and intercooperate to provide outputs for control of one or more local traffic controllers in a traffic control system or may be used to provide outputs for control of apparatus for control of the direction of traffic flow in a lane or lanes of one or more roadways.

It should be understood that the following description of the circuit operations of the schematic circuit part of FIG. 2a also describes the circuit operations of the circuitry within the corresponding blocks in the lower part of the drawing except for the fact that the description of the circuitry in the upper blocks will respond to one traffic flow actuation, for example, in bound traffic flow

actuation while the circuitry in the block form of the corresponding block in the lower section of FIG. 2a will respond to another traffic actuation, for example, out-bound traffic flow actuation. The two different traffic flows could be traffic that is proceeding along a roadway in opposite directions on the same roadway or may be on different roadways or may be the same traffic flow in the same direction on different roadways but any combination of different traffic flows.

For the purpose of description it shall be assumed that the traffic flows to be sensed are traffic flows traveling in a different direction, on the same two-way street, such as represented in FIG. 1 and referred to as inbound traffic flow and outbound traffic flow.

Information from inbound traffic vehicles, in the form of a voltage pulse is obtained, by a closure of a pair of contacts through actuation by each inbound vehicle of the vehicle detector 33, illustrated in FIG. 2a as a pair of open contacts surrounded by a broken line box and labeled 33, which voltage pulse causes a detector relay 64 to become energized. The vehicle detector 33 in FIG. 2a may be similar to the vehicle detector 33 in FIG. 1.

Information from outbound traffic vehicles, in the form of similar voltage pulses, is obtained by a closure of a pair of contacts through actuation by each outbound vehicle of another vehicle detector 34, illustrated as a pair of open contacts surrounded by a broken line box labeled 34, which voltage pulse causes another detector relay 64' to become energized. The vehicle detector 34 in FIG. 2a may be similar to the vehicle detector 34 in FIG. 1.

TRAFFIC CHARACTERISTIC MEASURING COMPONENTS FOR TWO TRAFFIC DIRECTIONS

Essentially, the preferred form of master controller, illustrated in the combined FIGS. 2a and 2b includes two identical components (both components illustrated in FIG. 2a, one component represented in block form the other component represented in circuit form), each for providing a voltage respectively which is proportional to a characteristic of a traffic flow essentially measured and determined through actuation of the vehicle traffic in the respective traffic flow. It shall hereinafter be assumed that the traffic flow characteristic measured is the volume of traffic. Each traffic volume measuring component may be adjusted respectively so that the certain number of vehicles, as desired, sensed over a certain period of time, the time period also being adjustable, will represent 100% traffic volume. The number of vehicles representing 100% traffic volume is determined by the road characteristics and represents the number of vehicles that may pass a particular spot during a certain period of time and still maintain substantially unobstructed flow of vehicle traffic.

A direct current voltage, which is proportional to one volume of traffic, for example, inbound traffic, is applied to a meter which may be calibrated to indicate traffic volume in convenient terms. The voltage which is proportional to the volume of traffic is also applied to a determining circuit which is associated with the relay 65 and upon the volume of traffic or the proportional voltage reaching a predetermined minimum value, relay 65 is energized. Thus the volume of inbound traffic below or above a predetermined minimum value may be determined according to the condition of the relay 65.

The voltage, which is proportional to the volume of inbound traffic flow, is also applied to the grid of a triode 70' in the component associated with the outbound traffic volume while a comparable connection applies the voltage, which is proportional to the volume of outbound traffic, to the grid of a triode 70 in the component associated with inbound traffic volume.

Thus the volume of inbound traffic, represented by a proportional voltage, provides partial control of the triode 70' via lead 69 by increasing or decreasing the bias

of the triode 70' as the volume of inbound traffic, represented by the proportional voltage applied from lead 120, provides partial control of the triode 70 via lead 69' by increasing or decreasing the bias on the triode 70 as the volume of outbound traffic (i.e., the proportional voltage applied via lead 121), increases and decreases.

The cathode voltage of tube 71 is established by the cathode voltage of tube 70 by virtue of the joining of the two cathodes. The grid of tube 71 is at a voltage which varies according to the voltage representing inbound traffic volume (voltage on lead 120) but is at a constant value below the voltage that is proportional to the volume of inbound traffic.

Thus conduction of tube 71 is controlled via grid control by an applied voltage that is at a constant value below the voltage that is proportional to inbound volume of traffic, and via cathode control by triode 70 which is itself controlled by grid control by an applied voltage proportional to outbound traffic volume. The circuit of triodes 70 will be recognized as a cathode follower.

DIFFERENCE CIRCUITS

The circuit directly associated with, and effecting the grid of triode 71 and the circuit directly associated with and effecting the comparable tube 71' in the block 54', below the circuit drawing 54 are both referred to as "difference circuits." The difference circuits 54 and 54' are adjustable, as desired, so that when the difference between the value of the two traffic flows is at or exceeds a predetermined difference the difference circuit associated with the higher traffic flow will respond. The predetermined amount or values over which one traffic volume must exceed the other traffic volume in order to provide conduction of one of the tubes 71 or 71' is individually adjustable, as desired.

These interconnected circuits, although individually adjustable, may provide conduction of tube 71, in the inbound traffic volume component so that when both traffic volumes are sufficiently close so as not to exceed a predetermined difference between the two volumes, or when both traffic volumes are substantially equal, relays 66 and 66' will both be deenergized and will provide for energization of relay 66 and deenergization of relay 66' when the volume of inbound traffic exceeds the outbound traffic volume by at least a predetermined value, as set in the difference circuit of tube 71. Energization of relay 66' and deenergization of relay 66 is provided when the volume of outbound traffic exceeds the inbound traffic volume by at least the predetermined value as set in the difference circuit of the comparable tube in the lower circuit.

With both volumes below their respective determined minimum volumes respectively the relays 65 and 66 of the inbound traffic volume component and the relays 65' and 66' of the outbound traffic component may all be in a deenergized condition.

RESPONSE TRANSLATING COMPONENT OF MASTER CONTROLLER

According to the preferred embodiment with the relays 65, 66, 65' and 66' deenergized the response translating component of the master controller, which translates the response combination of the several relays in the traffic characteristic determining, measuring and comparing components may provide an output to the individual local controllers which may be interpreted by the local controllers to cycle free of any offset condition or may be interpreted to operate in "average offset" with each individual local controller interpreting such output according to the position of a selector switch as described below.

With either or both relays 65 and 65' energized and both relays 66 and 66' deenergized the translating component may provide an output to the local controllers which may "call" for "average offset" of the local con-

trollers without permitting a selection between "free" or "average offset" condition. With relays 65 and 66 energized and relay 66' deenergized, and with 65' energized or deenergized, the translating component of the master controller will provide an output to the local controllers which may "call" for "inbound preferential offset" and with relay 65' and 66' energized and relay 66 deenergized, and relay 65 energized or deenergized the response translating component of the master controller will "call" for "outbound preferential offset."

The manner in which a "call" to the local controllers in the traffic control system is accomplished is by providing for energization or deenergization, in combination, of the several output leads which extend from the master controller (grouped leads 23 in FIG. 1) to the local controllers in the traffic control system. A "call" is established by translation of the condition or response of the several relays of the traffic characteristic determining, measuring and comparing components by the response translating component. The translated condition is expressed by energization or deenergization of the individual output leads, in combination.

Once a "call" to the local controllers has been established, a selected one of three timing mechanisms within the response translating component is initiated into operation and then electrically isolated from the selecting circuitry so that the established "call" will remain effective for at least a minimum period of time, after which the "call" may be changed, according to translation of the response of the several relays of the traffic comparing units to the traffic conditions then in effect.

It should be understood that the description of the circuit operations of FIG. 2a that follows and relates particularly to the circuit diagram in the upper portion of the figure, refers also to the circuitry within the blocks below, numbered with prime numbers, except that the detector 33 would be actuated by inbound traffic vehicles and detector 34 will be actuated by outbound traffic vehicles on different lanes of the same two way street, for example, and that the adjustable parts of the inbound traffic component may be adjusted individually and separately from the adjustable parts of the outbound traffic components. Further as previously noted the reference level for the determining circuit 54 will be controlled by the voltage applied via lead 120' while the reference level for the difference circuit 54' will be controlled by the voltage level of the lead 120.

TRAFFIC MEASURING UNITS—DESCRIPTION

Let it be assumed that the master controller 20 in FIG. 1 represents the master controller illustrated in the combined FIGS. 2a and 2b and that the vehicle detector represented by 33 in FIGS. 1 and 2a is located in the upper lane of roadway 24 as shown in FIG. 1, so as to be actuated by the individual vehicles in the inbound traffic flow and that the vehicle detector represented by 34 in FIGS. 1 and 2a is located in the lower lane of roadway 24 as shown in FIG. 1, so as to be actuated by the individual vehicles in the outbound flow.

Accordingly each time the vehicle detector 33 is actuated, its contacts are closed to complete a circuit to energize the inbound detector relay 64. Detector relay 64 will, upon energization close its contacts 80, which will illuminate detector indicator lamp 81, and will also close contacts 82 which may be used for other counting or indicating purposes as desired.

Energized relay 64 also opens contacts 83 and closes contacts 84. Between periods of actuation of detector 33, relay 64 is deenergized and contacts 83 are closed.

During such closed periods "bucket" capacitor 85 is charged with a voltage tapped off the potentiometer 86 at tap 89 in the cathode circuit of triode 90.

The plate of triode 90 is connected to a direct current (D.C.) source of approximately +300 volts, for example, represented by a plus in a square, and is normally conduct-

ing. Conduction of tube 90 is normally heavier than conduction of triode 91 partly due to the cathode circuit of tube 91 being connected through a neon tube 92 and resistor 93 to the +300 D.C. source, the neon tube 92 being a constant voltage drop device, and partly due to the grid control of tube 91 as described below.

The voltage at tap 89 is a percentage of the voltage across the cathode to ground circuit including potentiometer 86 and resistor 94 which percentage of the total voltage is adjustable according to the position of tap 89 on potentiometer 86. The percentage of voltage picked off by tap 89 of the potentiometer 86 from the cathode circuit of triode 90 is applied to capacitor 85, which is returned to ground, during closure of contacts 83 which are closed when relay 64 is in a deenergized condition.

Upon actuation of detector 33 thereby causing energization of detector relay 64 and subsequently the opening of contacts 83 and closure of contacts 84, the charge on capacitor 85 is "bucketed" into "tank" capacitor 95 which capacitor is also returned to ground. The preferred embodiment provides for capacitor 95 to be substantially larger than the capacitor 85, and it has been found that capacitor 95 may be four times larger in capacitance than the capacitor 85 although other ratios may be used if desired.

The action of charging the capacitor 85 between actuations of detector 33 and the subsequent bucketing or transfer of the charge on capacitor 85 to capacitor 95 upon actuation of the detector 33 will, upon multiple actuations, attempt to accumulate the charge on the capacitor 95 while the accumulated charge is slowly discharging through resistor 96 and part of potentiometer 99 to tap 100 to junction 101, through resistor 102 through to the negative D.C. supply, of the order of -150 volts D.C., for example, represented by a minus in a square.

Adjustment of tap 100 provides for increase or decrease of resistance in the discharge circuit of capacitor 95 and may be used to calibrate the 100% value of volume for a desired number of vehicles. As for example, 1000 vehicles per hour may be equal to 100% volume or 800 vehicles per hour may be equal to 100% volume, according to the position of tap 100 on potentiometer 99.

The charge on capacitor 95 is also applied through resistance 103 through the grid of tube 91. This provides control of the conduction of tube 91, the amount of conduction through tube 91 being proportional to the charge on capacitor 95.

The cathode circuit of tube 91 is connected to the +300 volt D.C. source through junction 104, neon tube 92 and resistor 93 which holds the conduction of tube 91 below the conduction of tube 90.

It should be noted that the junction 101 in the cathode circuit of tube 91 is maintained at slightly above ground zero, and thus in absence of actuation, and absence of the bucketing of the charge from capacitor 85 into capacitor 95, over a substantial period of time, the capacitor 95 will substantially fully discharge through the discharging circuit described, but the potential on the capacitor 95 will not go below ground.

The voltage applied to the junction 104 may be measured by a volt meter, if desired, and may serve as a measure of the instantaneous volume of inbound traffic.

Thus the last described circuit provides for feedback from the cathode of tube 91 through a constant voltage drop, such as the neon tube 92 and a resistor 105 to the grid of tube 90 to provide cooperation between the tubes 90 and 91. This interconnection will provide for conduction of tube 90 at a variable rate but somewhat above conduction of tube 91 so that as the measure of volume of traffic rises, which rise is represented by the amount of voltage applied at junction 104, the tube 90 will conduct more heavily and the charge applied to capacitor 85, which is a percentage of the cathode voltage of tube 90, will increase proportionally.

The increased charge on "bucket" capacitor 85 will be

transferred to "tank" capacitor 95 and will become more highly charged with each individual bucketing action. With a higher charge on capacitor 95 a voltage applied to the grid of tube 91 through resistor 103 will increase and cause tube 91 to conduct more heavily, however the discharge circuit for capacitor 95 may balance off the charge on capacitor 95 against the rate of discharge with the rate of discharge varied somewhat according to the amount of charge on the capacitor 95.

With tube 91 conducting at a higher rate the voltage at junction 104 is increased thus varying the potential applied to the grid of tube 90 causing tube 90 to conduct at a still heavier rate.

With substantially frequent actuations, as by vehicles traveling at a relatively heavy volume of traffic flow, the charge-against-discharge rate of capacitor 95 will balance off at a substantially high level, proportional to the volume of traffic so that the voltage at junction 104 may increase or decrease linearly, proportional to the volume of traffic.

The voltage at junction 104 is applied to a calibration circuit 106 which is provided to select a volume averaging time, as desired, by adjustment of the selector switch 109. The selector switch is illustrated in position #1 which may average the volume, which is in the form of a D.C. voltage with zero to +100 volts D.C. representing zero to 100% traffic volume over a period of time, in position #1 being a shorter term average than position #2 and position #2 being somewhat shorter than position #3 and progressively increasing the term average up to position 6 which is the longest term average illustrated.

The long term average volume picked off by switch 109, differs from the instantaneous volume at junction 101, and is applied to the capacitor 110 and to the grid of tube 112. The tube 112 is connected via its plate circuit to the cathode of tube 113 and thus provides a cascaded cathode follower. The plate of tube 113 is connected to the +300 D.C. voltage source with its grid circuit controlled by being connected to the +300 D.C. voltage source through resistor 114. The cathode of tube 112 is also connected to the +300 D.C. voltage source through the resistance 114 and further through a constant voltage device such as neon tube 115. This last described interconnection between tubes 112 and 113 sets the grid potential of tube 113 which in turn sets the plate voltage of tube 112. This essentially provides for elimination of the error apparent in any cathode follower operating over a wide voltage range, resulting from the fact that when the cathode voltage is low a relatively high negative grid voltage must be used to control the tube current, because there is a high plate voltage, as against the case in which the cathode voltage is relatively high and consequently the plate voltage is relatively low and the tube current is released, requiring low negative grid voltage.

The cathode of tube 112 is connected via resistor 116 to a minus 150 D.C. voltage source. The cathode voltage of tube 112 applied at junction 120 is a measure of the long term volume, the voltage being proportional to the volume of traffic having actuated the detector device 33, averaged over a period of time selected by adjustment of a selector switch 109.

The voltage applied at junction 120 which is also referred to as lead 120 as also applied to a meter 121 which may be calibrated in convenient terms to indicate the value of traffic volume. The meter is connected to ground through a potentiometer 122 which may be used for calibration purposes. A diode 123 is connected between the junction 120 and ground to prevent the cathode circuit of tube 112 from dropping below ground potential.

The potential at junction 120 is also applied through resistor 124 to terminal 125 which terminal may be connected to an external recorder or other device as desired.

Certain graphic recorders may require that the terminal be first connected to an amplifier then to the

recording device so that the load of the recorder will not load the circuit enough to effect the operation of tube 112. The potential at junction 120 or lead 120 is applied to match the resistors of the response determining circuits 51, 52 and 53 and to the difference circuit 54 via the lead 45 and from the lead 145 via lead 69 to the grid of tube 170' of the difference circuit 54'.

RESPONSE CIRCUITS—DESCRIPTION

It will be noticed that the response circuits 51, 52 and 53 are substantially the same except that response circuit 52 includes in its energizing circuit for relay 67 a contact 65-1 which is operated by energization of relay 65 of circuit 51 and circuit 53 includes in its energizing circuit for relay 68 a contact 67-1 which is operated by energization of relay 67 in circuit 52. This provides for a cascading response effect of the response circuits 51, 52 and 53 so that circuit 52 may only respond to the voltage on lead 120 only after response by circuit 51, resulting in closure of the contact 65-1, and circuit 53 may only respond to the voltage on lead 120 after circuit 52 has responded to the voltage on lead 120 and has closed contact 67-1.

The contacts 65-1 and 67-1 each may be electrical gates which normally individually prevent operation of the response circuit of which it is a part and when operated by its controlling component permits operation of its response circuit.

Thus the three response circuits 51, 52 and 53 may be operated in sequential steps with circuit 51 first operated and closing its contacts 65-1 in response circuit 52 so that response circuit 52 may then operate after which its contact 67-1 may close permitting response circuit 53 to operate each as set by the individual adjustments.

Adjustment of one response circuit as for example 51, would be the same for adjustment of circuit 52 and circuit 53 except that under normal operations the response circuit 52 would be adjusted to a higher voltage value than response circuit 51 and response circuit 53 would be adjusted to a higher voltage value than circuit 52. Therefore it may be seen that although individually set and adjustable a description of the operation and adjustment of circuit 51 would substantially describe the operation and adjustment of circuit 52 and 53.

The voltage potential on lead 120 is applied through matched resistors 126 and 129 with junction 130 between the matched resistors. The lower end of resistor 129 is connected to tap 131 on potentiometer 132 which potentiometer forms a part of a potential divider between a -150 volt D.C. source and ground, the potential divider including potentiometer 133, resistor 134, potentiometer 132 in parallel with potentiometer 135, resistor 136 and potentiometer 139.

The tap 131 may be adjusted so as to lift the triode 140 somewhat above the -150 volt D.C. supply, that is toward ground, or zero volts and, in effect hold the grid of triode 140 less negative than the negative voltage source.

A similar adjusting source is provided by matched resistors 141 and 142 being connected between potentiometer 135 via tap 143 from the cathode of tube 112 via lead 120.

The junction 130 is connected via normally closed make-before-break contact 65-2 which is controlled by the relay 65, which is in the plate circuit of triode 140. With the cathode of triode 140 connected to ground, zero, a small negative bias on the grid of triode 140 will cause the triode to conduct.

By adjusting the tap 131 on the potentiometer 132 of the potential divider the potential at junction 130 may approach ground zero from a normally negative potential as the potential on lead 120 increases from approximately ground zero. In this manner control of the triode 140 may be maintained so as to initiate conduction of the triode 140 at a predetermined potential applied to the

junction and lead 120 and through the resistor 126 to junction 130.

When the cathode voltage of tube 112, which represents the average volume of inbound traffic, and is applied through junction and lead 120 and hence through resistor 126 to junction 130, balances or overcomes the potential applied from the potential divider through resistor 129 to junction 130 so that the potential at junction 130 is at substantially ground zero potential or above, in a positive direction, the triode 140 will conduct and cause energization of relay 65. Thus this balancing circuit may provide for conduction or response of triode 140 and therefore energization of relay 65 at a certain level of volume as determined by the setting of the tap 131, as desired.

Upon energization of relay 65 the contact 65-3 closes and after closing opens the contact 65-2. Thus a second balancing circuit including matched resistors 141 and 142 and tap 143 of potentiometer 135 is connected from junction 144 so that adjustment may be made to have conduction of triode 140 cease at a lower level of volume than that at which conduction had been initiated.

The potentiometers 133 and 130 of the potential divider circuit are provided for calibration purposes so that the controlling potentiometers 132 and 135 may be calibrated and provided with dials, to facilitate easy adjustment of the response circuit and operation of the entire unit. The energization of relay 65 also closes contact 65-1 which will permit conduction of the tube 140-2 when the potential at junction 130-2 is balanced or overcomes the potential applied through the potential divider and potentiometer so that the grid of tube 140-2 approaches a ground zero potential and tube 140-2 begins to conduct. Conduction of tube 140-2 will cause energization of relay 67 which will close its contact 67-1 and permit conduction of tube 140-3 when the potential at junction 130-3 is sufficiently negative or close to ground.

DIFFERENCE CIRCUITS—DESCRIPTION

The voltage potential on lead 120 is also applied as illustrated via leads 145 and 69 and resistors 146' to the grid of tube 70' of the difference circuit 54' of the outbound traffic component associated with the outbound traffic flow. The lead 69 extends from the inbound traffic volume comparing unit shown here extending from the difference circuit 54 to the difference circuit 54' of the outbound traffic volume comparing unit and applies the potential carried by lead 120 which represents the volume of inbound traffic to the grid of tube 70' of the difference circuit 54'. A similar connection from the difference circuit 54' to the difference circuit 54 is provided as illustrated by the circuitry extending from the lead 120' and lead 145' to lead 69' which extends from the difference circuit 54' to the difference circuit 54 and through resistor 146 in difference circuit 54 to the grid of tube 70 thus applying the potential representing the volume of outbound traffic to the grid of tube 70.

The described interconnecting leads between the two components provide control of the tube 70 in the inbound traffic volume component by the outbound traffic volume component and similarly, control the tube 70' in the outbound traffic volume component by the inbound traffic volume component.

As may be seen in the inbound traffic volume component difference circuit 54, the plate of tube 70 is connected to the +300 volt D.C. source while the cathode of tube 70 is connected to the cathode of tube 71, both cathodes being connected in common through a resistance 149 to the minus 150 volt D.C. source.

When, for example, the outbound traffic volume increases and the potential, at junction 120' of the outbound traffic volume component increases proportionally. The potential at junction 120', applied to the grid of tube 70 of the inbound traffic component via lead 69' and resistor 146 causes conduction of the tube 70, the amount

of conduction being proportional to the value of the potential applied to the grid of tube 70. The cathode potential of tube 70 will be applied to the cathode of tube 71 so that in order that the tube 71 may conduct, the grid potential of tube 71 must be at least at a predetermined value relative to the potential applied to the grid of tube 70.

The grid potential of tube 71 is controlled by a difference circuit including potentiometers 150, 151 and 152 and resistor 153 connected between the potential applied via lead 120 and the minus 150 volt D.C. supply. Across the series connected potentiometers is a constant voltage drop source, such as neon tube 154. This parallel connected neon tube 154 is provided so that the voltage across the series connected potentiometers will remain constant while the potential at junction 120 varies with traffic thus providing a circuit which may cause conduction of tube 71 when the potential of junction or lead 120' is at a given value below the potential at junction or lead 120.

The potentiometers 150 and 152 provide a calibration for the dials associated with the potentiometers 151 and 160. The potential pickoff at tap 155 is applied through normally closed make-before-break contact 66-1 of relay 66, through resistor 156 through the grid of tube 71. The dual control of tube 71 via the grid connection and the cathode connection, is provided so that conduction of tube 71 may occur when the potential applied from junction 120 of the inbound traffic volume component is at a predetermined amount above the value at junction 120' of the outbound traffic volume component. Thus the amount of conduction through grid control via outbound volume component of tube 70 will set the cathode voltage of tube 71 and the difference circuit of the inbound traffic volume component will set the potential on the grid of tube 71 and thus through this dual control, the tube 71 will become conductive if the volume of inbound traffic is at or above the preset minimum difference between the outbound traffic volume and the inbound traffic volume level.

The relay 66 is illustrated connected between the plate of tube 71 and the +300 volt D.C. source. When tube 71 is not conducting, relay 66 is deenergized and its contacts 66-1 is closed and contact 66-2 is open so that initiation of conduction of tube 71 may begin at the potential of tap 155 and cessation of conduction may occur at the potential of tap 159 of potentiometer 160, the potentiometer 160 being connected in parallel with the potentiometer 151. When the relay 66 is energized due to the tube 71 conducting, the contact 66-2 is closed and the contact 66-1 is open so that the potentiometer 160 and its tap 159 is substituted for the parallel potentiometer 151 and its tap 155 initially connected in the grid circuit of the tube 71. This provides that initiation of conduction of tube 71 may be set at one difference level as adjusted by the setting of tap 155 and cessation of conduction of tube 71 may be set at another difference level, as by adjustment of tap 159.

Thus, at a certain desired level of inbound traffic volume, as represented by the voltage level at junction and lead 120, the tube 140 may be caused to conduct and cause energization of relay 65 which may permit the tube 140-2 to become conductive and cause energization of relay 67 when the voltage level at junction 120 reaches a higher level. Energization of relay 67 may permit conduction of the tube 140-3 and energization of relay 68 at another and higher voltage level at junction or lead 120 as set by the tap 131-3.

As the volume of inbound traffic increases from a low value to a higher value the response circuit 51 will be operated followed by operation of response circuit 52 at a higher level and followed by operation of response circuit 53 at a still higher traffic level thus providing response by the several response circuits in a cascading effect as the volume of inbound traffic increases.

Therefore it may be determined by the condition of

75

the relays 65, 67 and 68 or 65', 67' and 68' the relative volume of inbound traffic and the relative volume of outbound traffic respectively while the condition of relays 66 and 66' respectively may determine the relation between the inbound traffic volume and the outbound traffic volume relative to a predetermined difference between the traffic volumes.

Although the individual response circuits of the comparison unit of one traffic characteristic determining 10 measuring and comparing component may respond individually to preset minimum level of traffic volume the actual traffic volume as for example inbound traffic volume may be read on the meter 121.

It will be noted that the difference circuits 54 and 54' 15 of the traffic characteristic determining measuring and comparing components are arranged as constant difference circuits which will respond to a constant pre-set numerical difference in volume, for example the number of vehicles per hour difference. Since the numerical 20 difference remains constant, the percentage differential between the two volumes or the percentage difference between the two volumes is reduced as both volumes increase from a lower value. Thus when both traffic volumes are low a greater percentage of difference between 25 the two volumes will be required for operation of one of the difference circuits whereas when both traffic volumes are high a smaller percentage of difference between the two traffic volumes will cause operation of one of the difference circuits.

30 With the relays 65, 67 and 68 indicating response of the circuits 51, 52 and 53 respectively of the inbound traffic characteristic determining, measuring and comparing component and the relays 54', 67' and 68' indicating response of the circuits 51', 52' and 53' respectively of 35 the outbound traffic characteristic determining, measuring and comparing component and the relay 66 of the difference circuit 54 indicating response via difference circuit 54 to a condition whereby the inbound traffic is at least at a preset differential or more above the 40 outbound traffic and energization of relay 66' indicating response of the difference circuit 54' indicating that the outbound traffic volume is at or above a minimum differential with respect to the inbound traffic volume such 45 response of the several relays may be translated by the circuitry illustrated in FIG. 2b, herein referred to as the response translating component of the improved master controller.

RESPONSE TRANSLATING COMPONENT.—

FIG. 2b

50 Across the top of FIG. 2b represented in phantom form are the relays 65, 65', 66 and 66' over the left section of the drawing and relays 67, 67', 68 and 68' over the right section of the drawing with the individual relays 55 representing the relays similarly numbered in FIG. 2a.

55 Referring particularly to the left section of FIG. 2b the relays 65, 65', 66 and 66', in phantom form, individually control the contacts 65-6, and 65'-5, both normally open contacts, and 66-5 and 66'-5, both normally closed contacts, respectively. The contacts 65-6 and 65'-5 are arranged in parallel due to the connection 169. The contact 66-5 is in the energizing circuit of the relay 171 when the lock relay 201 is deenergized. The contact 66'-5 is in the energizing circuit of the relay 172 when 60 the lock relay 201 is deenergized. When the relays 65, 65', 66 and 66' are deenergized, as for example during traffic conditions in which both inbound traffic flow and 65 outbound traffic flow are below a minimum volume level as set by the adjustments of the response circuits 51 and 51' and neither volume level is sufficiently above the other so as to be at or above a preset difference between the two volume levels and with the switch 170 open as indicated, the relays 171 and 172 are deenergized as indicated. With the relays 65 and 65' deenergized the 70 relays 67 and 67' respectively would be deenergized which

in turn would hold relays 68 and 68' deenergized due to the cascading of the response circuits as previously described.

With the relay 171 deenergized its contacts 171-1, 171-2 171-4, 171-6, 171-8 and 171-9 are open and its contacts 171-3 171-5, and 171-7 are closed. With relay 172 deenergized its contacts 172-1, 172-4, 172-6, 172-8 and 172-9 are open and its contacts 172-3, 172-5, and 172-7 are closed. The network of contacts associated with the bracketed terminals 1 through 7 provides power to one or more of the terminals according to the condition of the relays 171 and 172 in combination, except for terminal 7 through which is applied power at all times. The network of contacts associated with the indicator lamps 181, 182, 183 and 184 provide power to illuminate one or the other of the indicator lamps. The contacts 172-8 and 171-8 when closed individually supply power to the indicator lamps 185, 186 and 187 in the right half of the drawing so that one or the other of these lamps may be illuminated. The contacts 171-9 and 172-9 individually control energization of the output lines 191 and 192 respectively which are two lines of the five grouped output lines generally labeled 23 in FIG. 1.

Thus when below minimum level traffic conditions are indicated by 51 the response of the traffic characteristic determining measuring and comparing component as by deenergization of the relays 65, 65' and 66' and 66, power is applied to terminals 5 and 6 from a source of positive supply through contact 171-3 and contact 172-5 to terminal 5 and also through contact 171-3 through lead 177 to terminal 6. Further indicator lamp 184 is illuminated via circuit from the source of supply through contact 172-7, 171-7 the indicator lamp 184 to ground. The contacts 171-8 and 172-8 are both open so that the indicator lamps 185, 186 and 187 are not illuminated. Further the contacts 171-9 and 172-9 are both open so that the output lines 191 and 192 of the grouped lines 23 are deenergized. Since the relays 65 and 65' individually respond to the circuit first responding to an increase of traffic volume of the associated traffic flow then when the relays 65 and 65' are both deenergized such response may be interpreted by the response translating component to indicate that the traffic in both traffic flows are below a predetermined minimum value respectively. With both relays 66 and 66' in a deenergized condition indicating failure of response of both difference circuits 54 and 54', this may be interpreted as indicating that neither traffic volume is sufficiently above the other to afford any preferential treatment to any one traffic flow over the other. Thus in such condition, as indicated, deenergization of the output lines 191 and 192 which may be used to control the offset of the local traffic controllers, may call for "free" operation of the local traffic controllers.

Thus according to the condition of relays 65 and 65' and 66 and 66', one or another of several offset conditions may be "called" for through the condition of the output lines 191 and 192 of the grouped output leads 23 from the master controller.

With either or both relays 65 and 65' energized and both relays 66 and 66' deenergized both relays 171 and 172 would become energized through pull-in circuits including either contact 65-5 or 65'-5, contact 66-5, contact 201-1, the coil of relay 171 to ground, for relay 171 and either contact 65-5 or 65'-5, contact 66'-5, contact 201-3, the coil of relay 172 to ground for relay 172.

With both relays 171 and 172 energized contacts 171-2 and 172-2 are closed to apply power to terminals number 1 and number 2. Contacts 171-4 and 172-6 are also closed to illuminate indicator lamp 181. Contacts 171-9 and 172-9 are closed to energize the output leads 191 and 192 respectively.

With both output leads 191 and 192 energized a call by the master controller may be made to the local controllers for operation at an "average" offset condition.

The condition of all four relays 65, 65', 66 and 66' deenergized would indicate that the response circuits 51 and 51' and the difference circuits 66 and 66' have not been operated due to the low traffic volume of both traffic flows.

It will be appreciated that although the output leads 191, 192, 193, 194 and 195 are shown completed through to ground by closure of their respective associated contacts, these leads may supply positive power when their respective contacts are closed or may operate relays or may have their respective contacts inverted so as to open a ground connection or open a positive supply connection.

It will also be appreciated that closure of switch 170, which may be manually operated or automatically operated serves to supply power as would be supplied via closure of contacts 65-5 and/or 65'-5 as above described. With switch 170 closed response or lack of response by the relays 65 or 65' would not be interpreted by the response translating unit. Closure of switch 170 would eliminate "free" offset output conditions. With relays 65 and 66 both energized and relay 65' energized or deenergized and relay 66' deenergized (or with switch 170 closed regardless of the condition of relays 65 and 65' and relay 66 energized and relay 66' deenergized) the contact 66-5 will be open and the pull-in circuit for relay 171 will not be completed. However, contact 66'-5 will be closed to complete the energizing circuit for relay 172.

With relay 171 deenergized and relay 172 energized, contact 171-3 will be closed and contact 172-4 will be closed to apply power to terminals number 6 and number 4. Contacts 171-5 and 172-6 will be closed to cause illumination of indicator lamp 182 and contact 171-9 will be open and contact 172-9 will be closed so that output lead 191 will be deenergized and lead 192 will be energized. This combination of output lead 191 deenergized and output lead 192 energized may call for the local controller to operate at an "inbound" offset condition, thus giving preference to inbound traffic over outbound traffic.

The condition of relay 66 energized and 66' deenergized would indicate that the difference circuit 54 has been operated and difference circuit 54' has not been operated. This condition indicates that inbound traffic volume is at least at or above the predetermined minimum value relative to outbound traffic volume.

With relays 65' and 66' both energized and relay 65 energized or deenergized and relay 66 deenergized (or with switch 170 closed regardless of the condition of the relay 65 and 65', and relay 66' energized and relay 66 deenergized) the contact 66'-5 will be opened and contact 66-5 will be closed. The pull-in circuit for relay 172 will be open at contact 66'-5 but the pull-in circuit for relay 171 will be completed and relay 171 will be energized and relay 172 will be deenergized.

Under such conditions contact 171-2 and contact 172-3 and power will be applied to terminals number 1 and number 3. Contacts 171-6 and 172-7 will be closed to illuminate indicator 183 and contact 171-9 will be closed and contact 172-9 will be open so that output lead 191 will be energized and output lead 192 will be deenergized.

The combination of lead 191 energized and lead 192 deenergized may call for the local controllers to operate at an "outbound" offset condition, thus giving preference to outbound traffic over inbound traffic.

The combination of relay 66' energized and relay 66 deenergized would indicate that the difference circuit 54' has been operated and difference circuit 54 has not been operated. This condition indicates that outbound traffic volume is at least at or above the predetermined minimum value, relative to inbound traffic volume.

Thus the master controller may "call" for one of several signal cycle offset conditions by its output leads 191 and 192 of grouped leads 23 (FIG. 1), and may in-

dicate that such call is being made by illumination of one of the indicator lamps 181 through 184.

At the same time as such "call" is being made power is applied to one or more terminals 1 through 6, with power constantly applied to terminal 7. Terminal number 1 has power applied to it when there is a "call" for "average" offset and when there is a "call" for "outbound" offset. Terminals numbered 2, 3 and 4 have power applied to them individually when there is a "call" for "average" offset, "outbound" offset and "inbound" offset, respectively. Terminal number 5 has power applied to it when there is a "call" for "free" operation. Terminal 6 has power applied to it when there is a "call" for "inbound" offset and "free" operation.

A switch 173, illustrated open, is provided so that the terminals number 2 and number 5 may be joined and both terminals have power applied to them during a "call" for "average" offset and during "free" operation.

It will be noticed that the energizing circuits for the relays 175 and 176, other than the holding circuits do not include a source of positive power. Such power may be obtained through terminal number 7 if the jumper connections J-1, J-2, J-3 and/or J-4 are connected such terminal. With jumper connections J-1 and J-4 disconnected from the terminals and jumper connections J-2 and J-3 connected to terminal number 7 the condition (energized or deenergized) of the relays 175 and 176 depend entirely upon the condition (energized or deenergized) of relays 67, 67', 68 and 68'.

This connection may provide complete control of the relays 175 and 176 by the condition of the relays 67, 67', 68 and 68' and is but one of the several modes of operation of the master controller.

Let it be assumed that the jumper connections J-1 and J-4 are disconnected and the jumper connections J-2 and J-3 are connected to terminal number 7.

With the relays 67, 67', 68 and 68' deenergized the relays 175 and 176 will be or remain deenergized. With relay 175 deenergized its contacts 175-3 and 175-5 are closed and contacts 175-1, 175-2, 175-4, and 175-6 are open. With relay 176 deenergized, its contacts 176-3 and 176-5 are closed and contacts 176-1, 176-2, 176-4 and 176-6 are open.

SELECTION OF MOTOR DRIVEN CYCLE TIMERS BY RESPONSE TRANSLATING COMPONENT FROM RESPONSE CIRCUITS

With both relays 175 and 176 deenergized indicator lamp 185 will be illuminated if either one or both contacts 171-8 and 172-8 are closed, and motor M-1 will be supplied with power via contacts 176-5 and 175-5, cam C2/C3, the coil of the motor M-1 to ground. Further, with both relays 175 and 176 deenergized contacts 175-6 and 176-6 are open and the output leads 193 and 194 are deenergized. The combination of the relays 67, 67', 68 and 68' all being deenergized would indicate that response circuits 52, 53, 52' and 53' have not operated due to the failure of traffic to increase to the level where response circuit 52 or 52' would operate. If the relay 171 or 172 or both were energized so as to close contact 171-8 and/or 172-8 the indicator lamp 185 would be illuminated to indicate that the motor M-1 was selected for control of the signal cycle length. The offset condition may be indicated by illumination of indicator lamp 184, the "free" condition indicator lamp.

With either or both relays 67 and 67' energized and both relays 68 and 68' deenergized the energizing circuit for relay 175 may be completed from jumper connection J-2 through contact 67-5 or 67'-5, contact 201-5 the coil of relay 175 to ground. The energizing circuit for relay 176 will remain open and relay 176 will remain deenergized.

Energized relay 175 will close its contacts 175-1, 175-2, 175-4, and 175-6 and open its contacts 175-3 and 175-5. Indicator lamp 186 will be illuminated since contact 171-8 or 172-8 or both contacts must be closed since relay

65 must be energized before relay 67 may be energized and relay 65' must be energized before relay 67' may be energized and therefore either one or both relays 171 and 172 would be energized and thus either or both contacts 171-8 and 172-8 would be closed. Therefore indicator lamp 186 would be illuminated for positive power through contact 171-8 or 172-8, lead 181, contact 176-3, contact 175-2, the lamp 186 to ground.

Further, contact 175-5 is open to break the driving circuit for motor M-1 and contact 175-4 is closed to complete the driving circuit for motor M-2 from positive power, contact 176-3, contact 175-4 cam contacts 2/3 to motor M-1 to ground.

Contact 175-6 is closed to energize output lead 193 and contact 176-6 is open holding output lead 194 deenergized.

Thus with relay 67 and/or 67' energized and relays 68 and 68' deenergized one or both traffic comparing units have responded to a level of traffic flow which is above the minimum traffic level (response of circuits 51 and/or 51') and at or above the second level (response by circuits 52 and/or 52') but below the third level (set by adjustment of circuits 53 and 53'). Further selection of motor M-2 and the combination of output 193 energized and 194 deenergized is provided to the local controllers which may be used to select a signal cycle length which may be different from that selected by other combinations of output lead conditions.

With relays 67 and 68 energized and/or relays 69' and 68' energized both relays 175 and 176 have their energizing circuits completed, with the energizing circuit for relay 175 completed as described above and with the energizing circuit for relay 175 completed from jumper J-3 via contact 68-5 or 68'-5, contact 201-7 the coil of relay 176 to ground.

Energization of relay 175 will reverse its contacts as previously described and relay 176 will close its contacts 176-1, 176-2, 176-4 and 176-6 and will open its contacts 176-3 and 176-5.

Closure of contact 176-2 completes a circuit to illuminate indicator lamp 187 and closure of contact 176-4 completes a circuit to drive motor M-3. Closure of contact 176-6 completes a circuit to energize output lead 194.

Therefore with energization of either one or both relays 68 and/or 68' the response translating unit may provide operation of the motor M-3 and the combined output leads 193 and 194 and illumination of lamp 187.

Thus according to the response of the response circuits 52 and 53 and 52' and 53' one of three motors is selected to drive a cam shaft and open and/or close cam contacts illustrated below the motor.

Each motor has its associated cam contacts, the cycle of which is illustrated in the cam chart below FIG. 1, labeled FIG. 5.

As illustrated when in a common position cam contacts C1/C2 are open, C2/C3 are closed C4/C5 are closed and C6/C7 are open. This condition is indicated by the shaded area in the cam chart. The length of time of one cycle depends upon the speed of the motor and the time required by each motor to complete a cycle may differ from the others. Therefore the cycle length may change according to the motor selected.

When a driving circuit for any one motor is completed it starts to drive its cam shaft while the other two motors remain still and their cam shafts and cam contacts remain still. As soon as the cam shaft of the driven motor is rotated out of the common position (the shaded area in FIG. 5), cam contacts C2/C3 open and cam contacts C1/C2 close and cam contacts C4/C5 open and relay

201 becomes deenergized the contacts 201-1, 201-3, 201-5 and 201-7 start to open and contacts 201-2, 201-4, 201-6 and 201-8 close. After the latter set of contacts 201-2, 201-4 etc. close the former set of contacts 201-1, 201-3 etc. open.

The relays 171, 172, 175 and 176 would then be iso-

lated from their energizing circuits and if any one or all of the relays had been energized those relays would remain energized through a holding circuit individual to each relay. If any one or all of the relays had been de-energized those relays would remain deenergized as the respective holding circuits would not have been completed.

When the relays 171, 172, 175 and 176 are isolated from their respective pull-in or energizing circuit the relays of the response circuits may change their condition without any effect on the response translating unit.

The condition of the output leads 191, 192, 193 and 194 remains unchangeable so long as the relays 171, 172, 175 and 176 are in their isolated condition.

When the relays have become isolated, the driving motor closes its cam contacts C1/C2 and opens C2/C3. This opens the initial driving circuit of the active motor and closes a self driving circuit so that the motor is isolated from the contacts of the relays 175 and/or 176.

After closure of the self-driving circuit of the active motor the cam contacts C6/C7 close and complete an energizing circuit for relay 205, through contacts of the initial driving circuit of the active motor.

Energized relay 205 closes its contact 205-1 which energizes output lead 195.

The active motor rotates the cam shaft, the speed of rotation depending upon the motor.

Thus an output from the master controller, to the local controllers may be maintained for a period of time depending upon the speed of rotation of the motor selected.

In the preferred form the master controller may select motor M-1 when operating in "free" and/or when the value of at least one traffic flow is at or above the minimum value adjusted by the setting of response circuit 51 or 51' or both but not at or above the value at which the associated circuit 52 or 52' will respond. Motor M-2 may be selected for operation when the volume of either one or both traffic flows are sufficiently high to cause response by response circuits 51 and 52 and/or 51' and 52'.

Motor M-3 may be selected for operation when either one or both traffic flows are sufficiently high to cause response by the response circuits 51, 52 and 53 and/or 51', 52' and 53'.

Since response of the response circuits, in sequential steps, is made in response to increase of traffic flow and it may be desired to vary the signal cycle length according to the amount of traffic the motor M-1 may cause rotation of its associated cam shaft in forty seconds, for example, while motor M-2 may cause rotation of its associated cam shaft in sixty seconds, for example and motor M-3 may cause rotation of its cam shaft in eighty seconds, for example. Obviously other motor causing rotation of a cam shaft at other speeds may be used, as desired.

Thus the selection of an offset and signal cycle length output control may be maintained for at least a minimum time.

JUMPER CONNECTIONS AT MASTER CONTROLLER FOR OFFSET AND CYCLE LENGTH SELECTION IN RELATION TO LEVEL RESPONSE CIRCUITS

It may be desired to control the signal cycle length cooperatively so that at a desired offset condition the signal cycle length may change if the volume of traffic is sufficiently high.

This type of coordinated control is provided for by connecting jumper J-2 to one of the terminals 1 through 6, as desired and connecting jumper J-3 to one of the terminals 1 through 6 as desired. The terminals J-1 and J-4 would be unconnected.

If, for example jumper connection J-2 was connected to terminal 3 then when power was provided via terminal 3 (when there is a call for "outbound" offset conditions) and traffic was sufficiently high to operate either or both relays 67 and/or 67' the relay 175 could be energized and

the output of the master controller would call for an out-bound offset with the signal cycle length controlled by operation of motor M-2.

Obviously various combinations of offset condition over cycle length may be provided for, according to the setting of the jumpers. By connecting jumper J-3 to terminal number 4 selection of motor M-3 may be obtained when there is a call for inbound offset and traffic is sufficiently high to cause energization of relays 68 and/or 68'.

10 If it is desired to provide a signal cycle length (selection of motor M-2 or M-3) according to offset selection above the jumper connections J-1 and J-4 may be connected to one of the terminals 1 through 6.

15 Thus with jumper J-4 connected to terminal 3 then when power is applied to terminal number 3 (upon call for outbound offset conditions), the motor M-2, for control of the signal cycle length, may be operated, therefore selection of the signal cycle length may be made according to the offset condition called for.

20 Of course, selection of a motor is also associated with selection of an output combination of the leads 193 and 194, as previously described.

25 Returning to the cam chart in FIG. 5, it will be noticed that just prior to completion of one complete cycle of the cam shaft the cam contacts C6/C7 open. This drops out relay 205 and causes contact 205-1 to open thereby deenergizing output lead 195. Then cam contacts C1/C2 open and cam contacts C2/C3 close and C4/C5 close. Closure of cam contacts C4/C5 cause energization of relay 201 which operates its contacts to electrically connect the relays 171, 172, 175 and 176 to their respective contact circuit network which may maintain the respective relay energized or cause deenergization of any one or all of the relays, according to the condition of the response circuit relays 65, 65', 66, 66', 67, 67', 68 and 68'.

30 It has been described how the various output lead combinations of energized and/or deenergized leads from the master controller may be obtained. The plan diagram in FIG. 1 may represent how the output leads may be extended to the local controllers in the control system, as by grouped leads 23. It should be noted that a common ground return may be added to the grouped leads 23, if needed, however such return lead is omitted, for convenience.

35 The individual output leads may be extended to the local controllers in the control system, which may include a local coordination unit, block FIG. 3, of FIG. 1, shown in circuit form in FIG. 3 and block FIG. 4 of FIG. 1, shown in simplified form in FIG. 4.

LOCAL COORDINATION UNIT OF FIG. 3 AND MASTER SELECTION OF LOCAL CYCLE MOTORS

40 Referring to FIG. 3 the grouped leads 23' represents the leads connected to the leads 191, 192, 193, 194 and 195 extending from the master controller. Identical numbers are used to indicate connecting leads between the master controller and the local coordination unit.

45 The relays 175L, 176L, 171L and 172L in FIG. 3 are controlled by the leads 194, 193, 191 and 192 respectively between FIG. 2b and FIG. 3, and the relays in FIG. 3 in effect repeat the condition of the relays 175, 176, 171 and 172 respectively, located in FIG. 2b.

50 The relay 205L in FIG. 3 is controlled by the lead 195 between FIG. 2b and FIG. 3, which lead is controlled by the condition of relay 205 in FIG. 2b with relay 205 controlled by the cam contacts C6/C7 of the operated motor.

55 Therefore it may be said that the relay 205L in FIG. 3 is controlled by the cam contacts C6/C7 of the operated motor in FIG. 2b.

60 As previously described the cam contacts C6/C7 are open during the time the offset, cycle length outputs and motor in FIG. 2b are selected by translation of the response of the relays of the comparing units. Thus during the time selection of offset and cycle length output and

cycle motor is made relay 205L in FIG. 3 is deenergized and its contact 205-5 is closed.

Since selection of offset and cycle length output, and cycle motor is expressed in the combination of relays 171, 172, 175 and 176 being energized and/or deenergized and the relays 171L, 172L, 175L and 176L in FIG. 3 substantially repeat the condition of the relays 171, 172, 175 and 176 respectively in FIG. 2b then, when the selection of cycle motor M-1 or M-2 or M-3 in FIG. 2b is made by the relays 175 and 176, selection of a corresponding cycle motor, M-10 or M-20 or M-30 in FIG. 3 may be made by relays 175L and 176L in a similar manner. Thus when cycle motor M-1 is selected by a combination of relays 175 and 176 to control the cycle of the master controller, motor drive M-10 may be selected by the corresponding combination of relays 175L and 176L to control the cycle of the local coordination unit. Therefore it may be said that motor M-1 in the master controller in FIG. 2b may be associated with motor drive M-10 in the local coordination unit in FIG. 3; motor M-2 in FIG. 2b may be associated with motor drive M-20 in FIG. 3 and motor M-3 in FIG. 2b may be associated with motor M-30 in FIG. 3.

Each motor drive in FIG. 3 drives a set of cam wheels, as for example motor M-10 drives cam wheels C31, C32, C33 and C34, with motor drives M-20 and M-30 driving a corresponding set of cam wheels.

Each cam wheel is independently adjustable so that the cam lobe may be positioned as desired.

Along with selection of one of the three motor drives, by the condition of relays 175L and 176L, the set of cam wheels driven by the selected motor drive are also selected from the other two sets of cam wheels.

For example with both relays 175 and 176 in FIG. 2b deenergized, representing very light traffic conditions, the relays 175L and 176L will also be deenergized. Contacts 5L-1, 5L-3, 5L-5 and 5L-7 are closed and 5L-2, 5L-4, 5L-6 and 5L-8 are open.

Closure of contact 5L1 completes a circuit from ground through closed contact 205-5, 5L-1, lead 310, motor M-10 to positive power. Closure of contact 5L-3 prepares a circuit from ground to the cam contact 311, which will close when the lobe of cam wheel C32 is rotated and lifts the contact 311 from below. Closure of contact 5L-5 prepares a circuit from ground to the cam contact 312 which contact will be closed upon being lifted by the lobe of C33. Closure of contact 5L-7 prepares a circuit from ground to the cam contact 313 which contact will be closed upon being lifted by the lobe of C34.

The broken line 320 indicates that motor M-10 drives cam wheels C31, C32, C33 and C34. The arrows indicate the direction of rotation. Broken line 330 and broken line 340 each indicate that the cam wheels through which the respective broken lines pass are driven by motors M-20 and M-30 respectively.

When the relay 175 in FIG. 2b, is energized, thereby causing energization of relay 175L in FIG. 3 and the relay 176 in FIG. 2b is deenergized thereby causing deenergization of relay 176L in FIG. 3 the combination of which may represent medium traffic conditions, then contacts 5L-2, 5L-4, 5L-6 and 5L-8 would be closed and motor M-20 would be selected for operation via a circuit from ground through closed contact 205-5, contact 5L-2, contact 6L-1, lead 325 to motor M-20 to positive power.

Closure of contact 5L-4 prepares a circuit from ground through contact 5L-4, 6L-3 to cam contact 321, contact 5L-6 prepares a circuit from ground through contact 5L-6, contact 6L-5 to cam contact 322 and contact 5L-8 prepares a circuit from ground through contact 5L-8, contact 6L-7 to cam contact 323.

When both relays 175L and 176L are energized, as for example during heavy traffic condition the motor M-30 and its associated cam wheels are selected for operation by completion of a circuit from ground through contacts 205-5, 5L-2, and 6L-2, lead 335, motor M-30 to posi-

tive power. Similarly, the set of cam wheels and their contacts, associated and driven by motor M-30 are made part of the prepared circuits via contacts 5L-4, 6L-4 to cam contact 331; contacts 5L-6, 6L-6 to cam contact 332 and contacts 5L-8, 6L-8 to cam contact 333.

Thus selection of a motor and its set of associated cams is accomplished for operation of the local coordination unit.

The speed of rotation of the individual motor of the local coordination unit may differ, one from the other and in the preferred form, the speed of rotation of the motor in the local coordination unit approximates the speed of the corresponding motor in the master controller.

As for example the speeds of rotation of motors M-1 in FIG. 2b and M-10 in FIG. 3 may be substantially equal, motors M-2 in FIG. 2b and M-20 in FIG. 3 may be substantially equal and motors M-3 in FIG. 2b and M-30 in FIG. 3 may be substantially equal.

Each motor M-10, M-20, M-30 includes a cam wheel C31, C41, and C51 respectively in its respective set of cam wheels. The respective cam wheels each control a cam contact 301, 302, and 303 respectively. When closed, each cam contact 301, 302 and 303 respectively completes a self-driving circuit for the motors M-10, M-20 and M-30 respectively.

For example when the cam lobe on cam wheel C31 lifts cam contact 301 the contact opens and breaks the self driving circuit. The motor M-10 must then be supplied power by an alternate circuit in order to operate. The alternate power circuit includes the contact 205-5, controlled by relay 205L, which relay responds to lead 195 which lead is controlled by relay 205 in the master controller which is controlled by the cam contacts of the selected motor in the master controller, which cam contacts C6/C7 are employed for synchronization purposes.

If the motor M-10 is at rest (stopped with cam contact 301 open), and contact 5L-1 is closed, the motor M-10 will be initiated into operation upon closure of contact 205-5. This provides a coordination point or common starting time for selected motor drives in the local coordination unit. Contact 205-5 remains closed only so long as relay 205L remains deenergized. If the output via lead 195 fails then relay 205L would be deenergized and the local controller could operate without coordination. If the motor M-10 is operating and rotates its cam wheel so that the cam contact 301 opens when the alternate power circuit through contact 205-5 and 5L-1 is completed motor M-10 will continue to operate and the local controller, through the local coordination unit, will be in synchronization or coordination with the master controller.

As described one motor of three motors, and a full set of cam wheels is selected as a unit. Each set of cam wheels include a homing cam wheel such as C31, C41 and C51 an average offset cam wheel, such as C32, C42 and C52, an inbound offset cam wheel such as C33, C43 and C53 and an outbound offset cam wheel such as C34, C44 and C54.

Selection of the motor and its set of associated cam wheels is made according to the condition of the relays 175L and 176L, which are responsive to the higher of the two traffic flows. From the selected set of cam wheels, one cam wheel may be selected according to the condition of the relays 171L and 172L, which in effect repeat the condition of relays 171 and 172 respectively in FIG. 2b, which are responsive to the relation between the two traffic flows.

For example with the master controller "calling" for average offset both relays 171 and 172 in FIG. 2b and therefore relays 171L and 172L will be energized and contacts 1L-1 and 1L-3 will be open and 1L-2 and 1L-4 will be closed and contacts 2L-1 will be open and 2L-2 will be closed.

The last described contact circuitry will prepare a circuit for completion by the cam contact if one of the cam

wheels C32, C42 or C52, or as described, by one of the cam contacts of the selected set of cam wheels and motor combination. Therefore the cam wheels C32, C42 and C52 may be considered the average offset cams.

With the master controller "calling" for "inbound" offset (relays 171 energized and 172 deenergized) a circuit is prepared for completion by the cam contact of one of the cam wheels C33, C43 or C53, therefore the cam wheels C33, C43 and C53 may be considered the inbound offset cams.

With the master controller "calling" for outbound offset (relays 171 deenergized and 172 energized) a circuit is prepared for completion by the cam contact of one of the cam wheels C34, C44 or C54, therefore the cam wheels C34, C44 and C54 may be considered the outbound offset cams.

Thus it may be seen that a motor and a set of cam wheels (one self-driving cam wheel, an average offset cam wheel, an inbound offset cam wheel and an outbound offset cam wheel) are selected by the condition of the relays 175L and 176L and from the selected set of offset cam wheels one cam wheel either average, inbound or outbound may be selected by the condition of relays 171L and 172L. A circuit through closure of the cam contact operated by the final selected cam wheel is completed to energize the relay 350 upon closure by the lobe of the rotated cam wheel.

Energization of relay 350 will only last so long as the cam contact of the selected cam wheel is closed.

Each cam wheel may be adjusted so that the cam lobe on the cam wheel is in a desired position relative to the zero degree position of the cam.

Although I have illustrated all the lobes of the same offset in approximately the same position it should be understood that cam wheels of the same offset may have their respective lobes adjusted to different positions as desired.

A switch 345 is illustrated closed to the average offset group of cam wheels. As previously described, in "free" operation the relays 171 (171L in FIG. 3) and 172 (172L in FIG. 3) are both deenergized and it may be desired to permit the local controller to operate "free" or to provide average offset when the master controller calls for "free" operation.

With the switch 345, as illustrated, the local controller will operate in average offset when a call for free is made by the master controller. With switch 345 in contact with terminal 346 the local controller may operate "free" when the master controller calls for "free" operation but will return to full coordinated control when a call for average, inbound or outbound is received.

A typical master controller "call" to the local controllers may be for medium traffic cycle length and average offset. The combination of relays in the master controller would be relay 175 energized relay 176 deenergized (medium traffic) and both relays 171 and 172 energized (average offset).

In the local coordination unit the corresponding local relay would be in a corresponding condition, relays 175L energized, relay 176L deenergized and both relays 171L and 172L energized.

Motor M-20 and its associated set of cam wheels would be selected for operation, so that when relay 205L (205 in FIG. 2b) became deenergized a circuit would be completed to drive motor M-20 out of its stop position through a previously traced circuit. At the same time a circuit is prepared, to be completed by closure of cam contact 321 when the cam wheel C42 is rotated by motor M-20 so as to close cam contact 321. The circuit may be traced from ground through contact 5L-4, 6L-3, cam contact 321, leads 348 and 349, contact 1L-4, contact 2L-2, relay 350 to positive power.

Thus any one of three motors, which may present three different cycle lengths, may be selected by the master controller according to the amount of traffic, and any

one of three offsets, plus "free" coordination, may be selected according to the relation between the traffic flows.

Thus some nine combinations of signal cycle length and cycle offset, plus "free" operation may be obtained 5 through cooperation between the master controller and the local coordination unit of the local controller.

The lead 400 represents one of the connections between the local coordination unit and the local signal switching device, FIGS. 3 and 4 respectively. As will 10 be described, the signal switching device may include selection between two or more splits or distributions of the signal cycle time among the various phases of the signal cycle.

Accordingly the contact circuitry of network 355 may 15 be provided for selection of one or the other of two split selections via a lead 401, in the signal switching device if the switching device provides for a selection between two splits. If the signal switching device provides for selection from among more than two splits, as for example four split selections, as represented in FIG. 4, a second contact circuitry network, which would be a duplicate of network 355, represented by network 356, may be employed so that two leads may be provided, 401 and 402, between the local coordination unit and the local 25 signal switching device.

Since the call for offset condition and signal cycle length is translated into the condition of the relays 171L, 172L, 175L and 176L then the output lead 401 may be energized or deenergized according to the position of 30 the switches (360 for example) and the "call" received from the master controller.

As illustrated with switch 360 open and all other switches closed the lead 401 will be energized (here shown connected to ground) whenever the "call" is not 35 for "free" operation.

By knowing the condition of the relays 171L, 172L, 176L and 175L according to the various offset and cycle length "calls" the switch which would be in the circuit 40 for the preselected "call" may be adjusted so that the output 401 is energized for selection of one split in the local signal switching device or deenergized, for selection of another split in the local switching device.

Two or more such contact circuitry networks could be employed if desired to provide various combinations 45 of outputs according to the number of splits from which selection may be made and depending upon the number of relay combinations available.

LOCAL SIGNAL SWITCHING DEVICE OF FIG. 4

FIG. 4 represents, partly in block and partly in schematic form, a simplified form of local signal switching device which may be a local traffic controller. It should be understood that although FIG. 4 is illustrated as a fixed time, rotary dial type local controller the controller 55 herein referred to as a signal switching device may be one of many different types, such as fixed time non-actuated, fixed time actuated, variable time semi-actuated, variable time full actuated or any other type local traffic controller which may require cooperation between a master controlled pulse, commonly referred to as a "yield control," and some other conditions in the local traffic controller to operate or start the local cycle.

One example of a local traffic controller that may 65 serve as a signal switching device in my present invention is illustrated in full circuit form in my U.S. Patent 2,883,643 issued Apr. 21, 1959, under the title Traffic Actuated Control Apparatus. The local traffic controller illustrated in my said U.S. patent may be substituted for the local traffic controller, or signal switching device represented in FIG. 4. Another example of a local traffic controller, subject to coordination control, which may 70 also be used as the signal switching device is the system of my present invention as taught by Harry A. Wilcox and John L. Barker in U.S. Patent 2,156,138 issued Apr. 25, 1939. Other local traffic controllers including yield

control features, familiar to those in the art, may also serve as a signal switching device.

Referring particularly to the local controller represented in FIG. 4, the preferred device may be capable of independently operating as a semi-actuated or non-actuated device, such as represented by local controllers 22 and 21 respectively in FIG. 1 with each type of controller capable of master control through a "yield" control circuit.

Generally the signal switching device in FIG. 4 includes a coordination input, or "yield" control lead 400, which may control a motor 410 when detector contact 429 is closed (when operated as a semi-actuated controller) or when switch 427 is closed (when operated as a non-actuated controller) and, the self driving circuit, through contact 415 is open.

When operating the motor 410 rotates the cam wheels C61, C62, C63, C64 and C65. The cam wheel C61 may be called a "homing" cam since the cam wheel C61 provides that motor 410 may drive to a "home" position and stop (when cam contact 415 opens by dropping into the depression on cam wheel C61, as shown).

The cam wheels C62, C63, C64 and C65 represent split cams each of which may distribute the time of one traffic signal cycle among the various signals, illuminated at any time during the cycle, according to where the lobes are set in the cam wheel.

The broken line on the radius of each cam wheel indicates the zero position of the cycle, or "home" position on cam wheel C61. The solid line radius of the cam wheels indicate a change in the signal display. Thus it may be seen that except for the first solid line counterclockwise from the broken line on each cam wheel, the time, precentagewise, distributed by each cam wheel differs from each other. Each lobe may be adjustable to a desired position on the cam wheel.

MASTER SELECTION OF SPLIT OF LOCAL CYCLE

The operation of relays 401R and 402R selects the desired split through closing a circuit to the cam contact controlled by the cam wheel providing the desired split of the signal cycle.

Upon closure of the cam contact (either 416, 417, 418 or 419), a prepared circuit will be completed to operate the motor magnet MM which may cyclically operate, in step-by-step or sequential fashion, a rotary switch or rotary cam or other stepping or line switch, represented by box 425, to cause illumination of the signals, such as represented as 30 and 31 in FIG. 1.

The pair of open contacts in broken line box 22D represents a vehicle detector such as vehicle detector 22D in FIG. 1.

Closure of the contacts of vehicle detector 22D causes energization of relay DR which may close its contact 426 and lock in through a holding circuit including contact 426, lead 433 and a normally closed contact in block 425 that may be opened by closure of a cam contact by lobe L3 and closed again by lobe L4 described relative to cam wheel C62.

The lock-in circuit for the relay DR may serve as a memory circuit.

The block 425 may also include a self synchronizing control which ensures that the rotary mechanism in block 425 remains in step with the cam wheels. This apparatus may be any of the familiar synchronizing controls familiar to those skilled in the art.

The speed of rotation of motor 410 is preferably slightly faster than the speed of the motor M-1 (M-10), M-2 (M-20) or M-3 (M-30) providing the shortest time cycle, which would rotate at the fastest rate of speed as among the various motors. The faster speed of 410 will ensure that the motor 410 will "home" at least before the end of the cycle. Thereby, motor 410 may be permitted to operate when the coordination or yield pulse is received via lead 400. Operation of motor 410 from

its "home" position is coordinated upon coordinated closure of contact 429 plus reception of the yield pulse via lead 400.

5 A switch 428 is provided for isolated operation of the local controller when the switch is closed.

Assume motor 410 is in its "home" position without relay DR having been energized. Further assume that both relays 401R and 402R are deenergized so that contacts 421 and 422 are closed thereby preparing a circuit through cam contact 416 for split control by cam wheel C62.

Since switch 427 is also here assumed open the local controller may rest in its "home" position until relay DR is operated by an actuation so that the contact 429 will be closed and a pulse via lead 400 is received while the contact 429 is closed to start motor 410.

When the cam contact (416-419) is open because of its lowered position by section a, the signal displayed to the main roadway (24 in FIG. 1) will be green with a red signal being displayed to the cross-street. Therefore the local controller may rest in main street green/cross street red.

25 Let it be assumed that the master controller is responding to the individual traffic flows along roadway 24 and is providing master control via the output leads 23 to the local coordination unit.

The local coordination unit duplicates the translated relay conditions of the master controller and duplicates the signal cycle length with the relay conditions selecting an offset condition and cycle length and a coordination or yield control pulse is provided according to master control and local selection.

LOCAL VEHICLE ACTUATED CONTROL

35 Let it now be assumed that vehicle detector 22D is actuated and relay DR is energized. Energized relay DR closes its contacts 426 and 429.

40 Assume the master controller approaches the end of its cycle of operation and the same or another offset and/or cycle length is selected, according to the present traffic condition on roadway 24. The output of the master controller, which is applied to each local coordination unit provides for duplication of the relay condition of the master controller by each local coordination unit of each local controller. Selection of a corresponding cycle length motor drive and the signal cycle offset cam associated with the selected motor drive is made according to the condition of the relays in the coordination unit which have duplicated the condition of corresponding relays in the master controller.

45 The selected motor in the local coordination unit will drive its cam which among which is the selected offset cam wheel, which will cause closure of a cam contact at a preset percentage point in the cycle, according to the position of the pre-adjusted cam lobe. Closure of the cam contact will energize a "yield" relay (350) and provide a "yield" pulse via contact 338 and lead 400 which may cause motor 410 to start driving its cam wheels.

50 Since contact 429 is assumed closed, an initiating circuit is completed to start motor 410 operating and as the cam wheel C61 is rotated clockwise the cam contact 415 lifted to be closed thereby completing a self driving circuit for motor 410.

55 The circuit operating the yield relay (350) in FIG. 3 will be opened as soon as the lobe in the selected cam wheel passes beyond its associated cam contact thus causing the cam contact to open and relay 350 to drop out, terminating the "yield" pulse over lead 400 by opening contact 338.

70 Thus the local signal switching device is initiated into operation at a point of time or offset, relative to the start of the cycle of the master controller, as set by the position of the lobe of the selected cam wheel with selection of the cam wheel made according to present traffic conditions.

Although the speed of rotation of motor 410 is not indicated as variable and, as described the cycle length may be lengthened or shortened according to the master controller output, the additional time of the master cycle that is longer than the cycle of the master in the local controller will be the time the local motor remains in the "home" position or additional time allocated to the main street green/cross street red period since it is assumed that the main street traffic is normally greater than the cross street traffic.

Referring to the cam wheel distribution of the cycle to the several signal combinations, area *b* indicates the relative time allocated to main street yellow/cross street red, area *c*, to main street red/cross street green, area *d*, to main street red and cross street yellow, and area *a*, to main street green/cross street red.

Closure of contact 416, for example by lobe L1, operates motor magnet MM to change the rotary control in block 425 to extinguish the main street green and illuminate the main street yellow signal while maintaining the cross street red signal. Lobe L2 causes operation of MM to change 425 to provide main street red and cross street green signals.

Lobe L3 operates MM to cause the holding circuit for relay DR to open and cause relay DR to drop out while the signals remain unchanged. Lobe L4 operates MM to close the holding circuit contact in 425 and again permits relay DR to be locked in when energized by traffic actuation so as to remember a vehicle which may not have had time to exit from the intersection before the cam wheel rotates sufficiently to cause lobe L5 to operate MM to terminate the cross street green and illuminate the cross street yellow. Lobe L6 operates MM to cause block 425 to display the main street green and cross street red signals.

Various combinations of cycle offset and cycle length developed in the master controller in the form of conditions of relays and selection of a motor and duplicated in the local coordination unit of the local controller provide for selection in the local coordination unit of a corresponding motor and a preset cam wheel which may permit a local signal switching device to begin its cycle of operation at a desired offset, for the prevailing traffic conditions, all cooperating with a synchronization circuit controlled in the master controller.

Although I have illustrated my improved control system of master controller, coordination unit and signal switching devices as motor operated, cam contact operating devices other forms of timing and cyclic or rotary switching devices known to those skilled in the art may be used which may provide similar results as those obtained from my illustrations herein.

It will also be appreciated that various further modifications or rearrangements of the illustrated embodiments of the invention or in parts thereof may be made without departing from the spirit of the invention within the scope of the appended claims.

I claim:

1. A traffic control system having a master controller for selection of various traffic control outputs for the control of the length of the time cycle of local traffic signal controllers and for controlling the offset of such time cycle with respect to a master time cycle, said master controller comprising

traffic characteristic measuring means for each of two traffic directions on a roadway respectively for providing an electrical voltage output respectively developed from a series of vehicles in traffic sensed in its respective direction, the level of said voltage output representing a characteristic of traffic flow of said vehicles and being substantially continuously variable over a range of values proportional to the measured traffic characteristic of the respective direction,

a first, a second and a third voltage level responsive

means individual to each measuring means for operating respectively in response to first, second and third levels of a progressively higher order of the respective said electrical output, each said level responsive means including

means individual thereto for adjusting the level for such response,

fourth responsive means individual to the respective said measuring means and comprising

adjustable difference circuit means coupled to both said electrical outputs for operating individually in response to the level of the said electrical output of the associated said measuring means being substantially in excess of the level of the other said electrical output of the other said measuring means by an adjustable predetermined difference,

offset control circuit means selectable for providing alternative offset traffic control outputs for offset of said time cycle of the local traffic signal controllers for one and the other of the respective two traffic directions,

response translating means for selecting said traffic control outputs in response to different combinations of operation and non-operation of said several responsive means for the respective directions, said translating means including

means responding to the operation of either or both of said first level responsive means for the respective directions and one or the other of said fourth responsive means respectively for selecting one or the other of said offset control output circuits respectively,

first, second and third individually selectable rotary timing means individually adjustable for providing first, second and third time lengths for said master time cycle respectively when selected for control of cycle length of said time cycle of said local traffic signal controllers,

and said response translating means further including further means coupled to the second and third level responsive means respectively for the two respective traffic directions for selecting for operation said rotary timing means in response to different combinations of operation or non-operation of said second and third level responsive means, said further means including

means for selecting for operation said first rotary timing means in response to non-operation of said second and third level responsive means,

means for selecting for operation said second rotary timing means in response to operation of either one or the other of said second level responsive means and non-operation of both said third level responsive means,

and means for selecting for operation said third rotary timing means in response to operation of one or the other of said third level responsive means.

2. A traffic control system as in claim 1 and in which said offset control circuits of said master controller include

preferential and non-preferential offset control output circuit means,

and in which said means for selecting said offset control output circuit means include

means for selecting for operation one preferential offset circuit for one direction in response to operation of the fourth responsive means for said one direction and non-operation of the fourth responsive means for the other direction, means for selecting for operation another preferential offset circuit for said other direction in response to

operation of the fourth responsive means for said other direction and non-operation of the fourth responsive means for the first direction, means for operating the non-preferential offset circuit means in response to operation of either of the first level responsive means for the respective directions and non-operation of both of said fourth responsive means for the respective directions, and means for selectively coupling desired individual of said first, second and third rotary timing means via 10 said rotary timing selecting means to said offset circuit selecting means for selection of said rotary timing means for desired cycle lengths in conjunction with selected offset output circuits by desired combinations of the respective fourth responsive means and the respective first, second or third respective level responsive means.

3. A traffic control system as in claim 1 and in which said response translating means includes two pairs of relays, the first pair of relays being coupled to the first 20 and fourth responsive means to be operated selectively thereby and coupled to said offset control circuit means to so select said offset control circuit means by operation of one or the other respectively of said first pair of relays in response to said different combinations of operation of said first responsive means and said fourth responsive means, and the second pair of relays being coupled to said second and third responsive means to be operated selectively thereby and coupled to said rotary timing means for so selecting for operation one of said rotary timing means by operation of one or the other respectively or both of said second pair of relays in response to said different combinations of operation or non-operation of said second and third responsive means.

4. A system as in claim 1 and said master controller 35 further including

a plurality of terminals, circuit means controlled by said offset output selecting means for selectively connecting power to one or another of the terminals of the said plurality, 40 means for selectively connecting said rotary timing selecting means to one or another of said plurality of terminals so that said rotary timing selecting means is controlled by said offset output selecting means.

5. A system as in claim 1 and including 45 a local traffic signal switching controller, adapted to

be operated cyclically for a traffic signal control cycle,

a plurality of cyclic timing means in said local controller, said cyclic timing means being individually selectable for so operating said controller in desired cyclic relation to said selected rotary timing means of said master controller, and means for selecting one of said last named cyclic timing means for so operating said local controller in relation to the selected rotary timing means in response to said means for selecting said rotary timing means in said master controller.

6. A system as in claim 5 and including multiple offset control means in each of said cyclic timing means in said local controllers for determining said cyclic relation of said local controller when selected,

and means for selecting any desired one of said offset control means for such determining operation in the selected timing means in response to said offset output selecting means of said master controller.

7. A traffic control system as in claim 6 and including further cyclic timing means in said local controller each said further cyclic timing means including

multiple alternative selectable split control means for so operating said local controllers in different distributions of signal periods in said signal control cycle when selected,

and means for selecting any desired one or another respectively of said split control means for such operation in the selected further cyclic timing means in response to said selective operation of selected said offset output circuit means and of said rotary timing selecting means of said master controller.

UNITED STATES PATENT OFFICE
CERTIFICATE OF CORRECTION

Patent No. 3,241,107

March 15, 1966

Charles L. Du Vivier

It is hereby certified that error appears in the above numbered patent requiring correction and that the said Letters Patent should read as corrected below.

Column 4, line 1, for "The output of each traffic (D.C.) voltage which may" read -- The output of each traffic determining and measuring unit is expressed in a direct current (D.C.) voltage which may --; column 9, line 55, for "degrees of" read -- degrees or --; column 15, line 32, for "values" read -- value --; column 16, before line 32, insert the following paragraph:

The relays 67 and 67' and 68 and 68' in Fig. 2b control the network of contacts and circuitry for providing translated information relative to magnitude of volume for selection of one motor of three motors and selection of an output to the local controllers which may control the time length of the signal cycle. --.

Signed and sealed this 26th day of November 1968.
